UNITED STATES PATENT OFFICE

HERBERT M. FRIENDLY, OF CHICAGO, ILLINOIS

TELEPHONE SYSTEM

Application filed December 6, 1930. Serial No. 500,531.

The present application is a continuation in part of my application Ser. No. 197,088, filed October 17, 1917.

Objects

The present invention, in its exemplary embodiment disclosed herein, is directed to an automatic telephone exchange system incorporating a number of private automatic exchanges wherein provision is made for passing calls from one station to another in a private automatic exchange so that stations may be successively called and disconnected by automatic means, while holding the seizure of the trunk line from the main exchange to the private automatic exchange.

The system of the present invention examples a number of different embodiments of the invention each having a specific method of operation, adapted to the particular requirements of service of the various private automatic exchanges.

Fig. 1 shows a calling automatic telephone A which has access through suitable intermediate switches, not shown, to switch B. The switch B, in turn, has access to the switches C, D, E and F. The switch B may therefore be the well known selector shown on page 78 of Hershey's book *Automatic Telephone Practice*, copyrighted, 1917. The switches C, D, E and F may be the well known selector-repeater shown on page 113 of the said Hershey book. That is, a call may be initiated at telephone A, causing a line switch, not shown, but as shown on page 55 of the said Hershey book, to plunge in and seize a first selector, not shown, like switch B. The latter said switch will then be operated responsive to the first digit series sent from the dial at telephone A to extend the connection to a second selector, not shown, like switch B. The latter said switch will then be operated in accordance with the second digit series to extend the connection to a third selector, not shown, like switch B. The latter said switch will then be operated in accordance with the third digit series to extend the connection to fourth selector B. The selector B will then be operated in accordance with the fourth digit series to extend the

connection to a selector-repeater C, D, E or F. The one of the last said switches seized will then be operated in accordance with the fifth digit series to select one of the trunks of the desired private automatic exchange.

The main exchange, in which the said switches C, D, E and F and antecedent switches are located, is assumed to be of the five-pull range. Of course, the range may be made less, employing correspondingly fewer selectors like B, or it may be made greater, employing correspondingly more selectors like B. It has not been deemed necessary to detail the switch train in the main exchange for extending calls from over the trunk lines to the private automatic exchanges, since the main exchange switch arrangement up to the trunk lines leading to the private automatic exchanges involves switches and arrangements well known before the parent application was filed, the present invention thus being confined to the private automatic exchange ends of the trunks, and arranged to cooperate with the well known main exchange arrangements for handling outgoing and incoming traffic over trunks having exactly two conductors which are used for talking and operating. These various private automatic exchange trunks are exemplified by 1-2, 3-4, 5-6, and 7-8, there possibly being more than one such trunk for each private automatic exchange.

A switch train involving the line switch LS, first selector C'', second selector D'', third selector E'' and connector F'', leading to a telephone B'', is shown in Fig. 1 for completing calls from a private automatic exchange over the trunk 1-2 into the main exchange. The line switch LS may be like shown on page 55 of the said Hershey book. The selectors C'', D'' and E'' may be like shown on page 78 of the said Hershey book. The connector F'' may be like shown on page 35 of the said Hershey book, it being noted that its leading-in talking conductors are reciprocated with respect to the windings of the line relay forming the front-bridge when the called party responds.

Fig. 2 shows the private automatic exchange attendant operator's circuits and are

so associated with the pair of switch elements Figs. 3 and 4 and the connector-selector Q^s in Fig. 8 that calls may be received from the main exchange and passed by the operator through the agency of the elements Figs. 3 and 4, and calls may be made to the main exchange over the trunk line from the operator's switchboard or calls may be extended to the main exchange by directive control from a telephone of the private automatic exchange.

Figs. 3 and 4 show an interlinked pair of switch elements or duplex connector, individual to the trunk 1—2.

15 Fig. 3A shows the arrangement of the private bank terminals of a group of three lines accessible from the switch elements Figs. 3 and 4.

20 Fig. 3B, which attaches above Fig. 3, shows the arrangement of four telephone lines, which are accessible from the pair of switch elements Figs. 3 and 4, and also a connector-selector like Q^s in Fig. 8.

25 Figs. 5 and 6 show an interlinked pair of switch elements or duplex connector, individual to the trunk 3—4.

30 Fig. 5A shows the arrangement of the private bank terminals of a group of three lines accessible from the switch elements Figs. 5 and 6.

35 Figs. 7 and 7A attaches above Fig. 5, and show attendant operators' trunk circuits cooperative with Figs. 5 and 6.

40 Fig. 8 shows a connector-selector Q^s having access to the trunk 1—2 and also the local telephone lines accessible from switch elements 3 and 4.

45 Fig. 8A shows an alternative relay 832, with respect to relay 813 in Fig. 8 for rendering a line having access to switch Q^s unbarred from selecting main exchange trunks as 1—2 on the 0 level of switch Q^s .

50 Fig. 8B shows the bank terminals of the 1 level that are swept by wipers 801 and 802.

55 Fig. 8C shows the bank terminals of the 0 level that are swept by wipers 801 and 802, together with the discriminating relay 840.

60 Fig. 9 shows the holding-trunk accessible from the wipers of switch elements Figs. 16 and 17 through the first set of bank terminals of the 4 levels, and through the second set of bank terminals of the 4 levels of the connector-selector Q^s corresponding to connector-selector Q^s , the bank terminals of local lines being commonly positioned in multiple, accessible from the switch elements Figs. 16 and 17 and the connector-selector Q^s .

65 Fig. 10 shows one of the attendant's trunks, which said trunk is accessible from the wipers of the switch elements Figs. 16 and 17 through the first set of bank terminals of the 3 levels.

70 Fig. 11 shows an operator's switching

cord-pair cooperative with Fig. 10 and also with Fig. 8.

Figs. 12 and 13 show an interlinked pair of switch elements or duplex selector, individual to trunk 5—6.

75 Fig. 14 shows four of the telephones accessible from the connectors shown in Figs. 19, 20 and 21, in common.

Fig. 15 shows the toll operator's plug and cord cooperative with a trunk leading to the 75 duplex connector elements 18 and 6.

Figs. 16 and 17 show an interlinked pair of rotary switch elements or duplex connector, individual to trunk 7—8.

80 Fig. 18 shows a rotary duplex toll connector element cooperative with element Fig. 6.

Figs. 19, 20 and 21 are similar connectors which are commonly accessible from the selector elements Figs. 12 and 13 and which have common access to the telephone lines 85 shown in Fig. 14.

85 Figs. 22, 23, 24, 25 and 26 show diagrams indicating the manner of assembling the Figs. to produce the circuits which will be referred to in the descriptions to follow.

Equipment

The various duplex connectors of corresponding private automatic exchanges each correspond to a trunk line, so that for each 95 trunk line there would be a duplex connector and these duplex connectors will have common access to local telephones and operator's trunks at corresponding bank positions. That is, a call received over any trunk of a 100 group will be extended through a duplex connector element by the same operation to a local line, so that the calling party or passing party will not have to be informed as to the particular trunk employed. Calls made locally are effected through a connector-selector 105 similar to Q^s in Fig. 8, wherein the local lines are common to the duplex connectors and the connector-selectors. It is noted that all the 110 duplex connector elements are group-selecting, so that the various levels may be divided into line groups, wherein the first line of the group would ordinarily be directly selected, and if this line is encountered busy, the switch element will thereupon hunt and 115 seize the first idle line of the group encountered, wherein if all the lines of the group are busy a tone will be applied to the leading-in trunk, and the switch locked against testing outside of the group.

120 These duplex connectors provide for a party in the main exchange directing a connection to the leading-in trunk of a said connector and then operating one of the elements thereof into connection with a local line, 125 whereupon the party on the local line can operate the companion element into connection with another local line, or the latter may be alternatively done by the party in the main exchange. This introducing of a line into 130

the connection subsequently to the first connection to a local line is referred to as "passing a call". There are a number of special operations for meeting various switching conditions which will be pointed out in detailing the operations of the various types of duplex connectors exemplified, which are those shown in Figs. 3-4, 5-6, 16-17 and 18-6.

The trunk line 5-6 terminates in the duplex selector elements Figs. 12 and 13, and these elements have common access to connectors for completing connections to telephone lines.

The duplex selector shown in Figs. 12 and 13 has access to connectors Figs. 19, 20 and 21, which latter have common access to local lines, and passing of calls may be made by sending three digits as the capacity of the private automatic exchange is 1000 lines as against 100 lines where the duplex connectors referred to are employed. Any suitable method of interconnecting the local lines may be employed, bearing in mind that the connector-selector Q^s in Fig. 8 would not answer, since it only has access to 100 line terminals. There are a number of special operations involving these switches which will be pointed out in detailing the operations of the duplex selector and cooperating connectors. There would be a duplex selector for each trunk line terminating in the private automatic exchange, and these would have common access to the cooperative connectors.

The various telephones are of the series 35 automatic type, although any suitable type may be employed.

The following U. S. patents and application of applicant are referred to. These all bear more or less upon the general function commonly present among them of affording means for passing calls from a called telephone to another called telephone, and where the passing operations may be continued indefinitely from one telephone to another. However, these all cover systems having different specific object and operation. It is pointed out that the scope of the claims in the present application differ from the claims made in other of applicant's said patents and application. Patent #1,441,791, granted Jan. 9, 1923, on an application filed June 11, 1917; Re-issue Patent #16,638, granted Apr. 8, 1930, in an application originally filed Feb. 17, 1921; Patent #1,628,359, granted May 10, 1927, on an application filed May 3, 1921; Patent #1,504,337, granted Aug. 12, 1924, on an application filed May 16, 1921; pending application, Ser. No. 509,263, filed Oct. 21, 1921; Patent #1,776,021, granted Sept. 16, 1930, on an application filed Jan. 20, 1922; Patent #1,776,022, granted Sept. 16, 1930, on an application filed Feb. 10, 1922.

In the specifications, when reference is made to a relay which is shown in the drawings to have a core slug at its lower end, it

will be understood that such relay is slow-releasing, that is, requires an appreciable time, longer than un-slugged relays, to de-actuate after being deenergized. Also, when a relay is said to be energized, without qualification as to being marginal, it will be understood as operatively energized so that it actuates.

Various assumed calls will now be exemplified to show certain operations, and make apparent other operations not specifically pointed out.

Call from telephone A in Fig. 1 to the operator's position in Fig. 2

With reference to diagram Fig. 22, the calling party at telephone A will initiate a call and operate the calling device in accordance with the numerical position of the trunk line 1-2 leading to the private 85 automatic exchange. This will complete a connection from the telephone A through switches B and C to trunk line conductors 1 and 2 shown in Figs. 1, 8 and 2. A circuit can now be traced from the upper winding of relay K^2 in Fig. 2, make-before-break springs, 201, 202, spring 203, sleeve spring 204 of jack j , springs 205, 206, trunk conductor 1, through telephone A, trunk conductor 2, springs 207, 208, tip spring 209 of jack j , spring 210, make-before-break springs 211, 212 to lower winding of relay K^2 , the latter said relay actuating.

A circuit can now be traced from ground, springs 217, 218, conductor 219, to glow the busy lamp 220, and through spring 221 to the winding of cut-off relay P^2 , the latter said relay actuating. Busy-ground is now applied through spring 222, conductor 223, to guard the trunk having line conductors 1 and 2 against seizure from the switches such as Q^s , shown in Fig. 8. A circuit can also be traced from ground, spring of key k^2 , spring 224 on relay H^2 , spring 225, spring 262 on relay E^2 to calling lamp 226, the latter said lamp glowing.

Upon the operator noting the glowing of lamp 226, she will respond by manipulating key k^2 . This will apply ground to energize the winding of relay D^2 . Ground will now be applied from spring 227 on relay D^2 through spring 228 to energize the winding of relay L^2 . Ground will now be applied to make-before-break spring 229, spring 230, to energize the winding of relay H^2 . Relays K^2 , D^2 , L^2 and H^2 are now actuated. Spring 232 now applies ground to conductor 219 to maintain the lamp 220 glowing, and the relay P^2 energized.

When relay H^2 actuated it reversed the relationship of trunk conductors 1 and 2 with respect to the windings of relay K^2 , this therefore reverses the direction of current traversing calling telephone A. A circuit can at this time be traced from the opera-

5 tor's telephone through inside spring of relay G^2 , inside springs of relay D^2 to the trunk conductors 1 and 2 over an obvious path. The operator can now talk with the calling party at telephone A.

6 *Extending call to telephone A'*

7 It will now be assumed that the calling 10 party at telephone A desires to talk with a party in the private exchange located at telephone A' in Fig. 3B, the numerical position, or number, of which is "21".

8 It will be noted in this connection that 15 when relay D^2 actuated, ground through spring 235 is applied through the springs of the dial Z^2 , springs 236, 237, 238, to the talking conductor 239 which leads through the upper winding of line relay A^3 in Fig. 3 to 20 grounded battery. Relay A^3 will energize under the condition and ground will be applied from spring 301 to energize relay B^3 . Ground will be applied from spring 302 to 25 conductor 219. Spring 302 applied ground to conductor 240. Ground from conductor 240 applied through the make-before-break spring on relay L^2 will hold relay H^2 energized in the event key k^2 is restored.

30 The operator is now ready to operate the dial in accordance with the telephone number "21". The first series of two impulses corresponding to digit 2 will cause the relay A^3 in Fig. 3 to retract its armature two 35 times in correspondence thereto. Upon the first retraction of spring 301 ground will be applied over conductor 304, spring 241 on relay K^2 in Fig. 2, conductor 242, spring 305 on relay B^3 in Fig. 3, winding of series relay C^3 , winding of the vertical magnet, side-switch wiper e^3 to grounded battery, the vertical magnet operating two times to step the wipers 306 to 309 into alignment with the 2 level of bank terminals. The armatures of relays B^3 and C^3 will sustain over 40 the lapse between the impulses, and the relay C^3 will deactuate consistent with its slow-releasing characteristic following the last 45 impulse of the series. The off-normal springs operate responsive to the first impulse when the wipers move from normal position.

50 At the time that relay C^3 actuates ground from spring 310 energizes interrupter relay Q^3 and also applies ground to the inside winding of the private magnet N^3 , actuating the private magnet and maintaining it 55 energized until the termination of the series of two impulses. Upon the deactuation of relay C^3 , relay Q^3 and the private magnet N^3 will deactuate, the latter causing the side-switch wipers e^3 and f^3 to move into 60 their second positions. Upon the second digit 1 being sent from the dial Z^2 the relays C^3 and Q^3 will again actuate, and the private magnet will again actuate. The side-switch wipers e^3 and f^3 being in their 65 second positions the rotary magnet will be

70 operated instead of the vertical magnet, which will cause the wipers 306 to 309 to move in and come to rest on the first set of bank terminals 312 to 315, respectively, of the 2 level.

75 It will first be assumed that bank terminal 315 constitutes busy-ground due to the corresponding line being busy. Under this condition when relay C^3 deactuates following the impulse corresponding to second digit 1, and ground is thus removed from the inside winding of the private magnet. Busy-ground derived from bank terminal 315 is now applied over wiper 309 side-switch wiper e^3 , outside winding of the private magnet to grounded battery, holding 80 the private magnet actuated.

85 If it is further assumed that the line "21" is the first one of a group of three lines, bank terminal 314 would be free of connections. A circuit can now be traced from ground, spring 310, spring on relay Q^3 , spring on private magnet, upper inside 90 spring on relay E^3 to the winding of the rotary magnet, the latter operating to step the wipers to the second set of bank terminals. At the time the rotary magnet thus operates, ground is applied through its contact to energize to relay Q^3 , and the inside winding 95 of the private magnet to maintain it actuated until the wiper 309 will come to rest on a bank terminal of the second set, not shown.

100 The energization of the relay Q^3 from a contact on the rotary magnet interrupts the circuit to the rotary magnet, so that its armature will retract in readiness to be re-attracted to step the wipers another step when the relay Q^3 deactuates, in the event that ground were found by wiper 309, which would serve, as before, to hold the 105 private magnet energized.

110 *Group selecting operation*

115 In this connection, Fig. 3A is referred to. This represents the private bank terminals of a group of three lines corresponding to lines "21", "22" and "23" accessible from the switch element Fig. 3; that is, the first three pairs of bank terminals of the 2 level 120 swept by wipers 308 and 309. It will be noted that the third pair of bank terminals in Fig. 3A has a conductor 317 tying them. It will thus be seen that were the bank terminal 318 busy-grounded when encountered by wiper 309, the companion bank terminal swept by wiper 308 would also constitute busy-ground. Therefore, if the wipers 308 and 309 are hunting over busy-grounded bank terminals, driven by the 125 rotary magnet in successive steps, when the last line of the group is found busy, not only will the wiper 309 find ground potential to maintain the outer winding of the private magnet energized, but this ground will be applied over wiper 308, spring 320, 130

make-before-break spring on busy relay E^3 , spring 322, winding of relay E^3 , side-switch wiper f^3 in second position to grounded battery, the relay E^3 actuating.

5 *Applying busy-tone when all lines of a selected group are encountered busy*

In this connection, it will be noted that a circuit path can now be traced from spring 321 on relay E^3 , lower off-normal spring, conductor 323, spring 243 on relay F^2 in Fig. 2 to ground. A locking circuit will thus exist from the latter said ground through make-before-break spring 321, spring 322, to the winding of relay E^3 , and this will endure regardless of any condition existing on the private bank terminal last encountered busy. Spring 321 also applies ground to lock the private magnet by its inside winding. Busy-tone from source T^4 in Fig. 4 will be applied over conductor 401, lower middle spring on relay E^3 , lower spring on relay L^3 , talking conductor 324, springs 245, 246, 247, operator's telephone, springs 248, 257, 258, conductor 239 to upper winding of relay A^3 in Fig. 3. The operator will thus perceive the busy-tone and it will also be perceived by the calling party at telephone A over an obvious circuit path, having in mind that relay K^2 is energized in series with telephone A.

Operator may restore switch element Fig. 3 from busy line

35 The operator may, in view of the back-bridge relay K^2 not being energized, cause the wipers of the switch element Fig. 3 to restore to normal by maintaining the key k^2 operated, and then operating the key e^2 to in turn energize the relay G^2 , which will cause obvious circuit changes to open the path from the dial Z^2 to the upper winding of relay A^3 . Relays A^3 and B^3 will become deenergized. Then, upon relay B^3 deactuating, following the deactuation of relay A^3 , ground will be applied through the spring 302, upper off-normal spring, conductor 325, spring 249 on relay F^2 in Fig. 2, conductor 250, spring 326 to the release magnet, the release magnet operating to restore the wipers of switch element Fig. 3. The latter operation will open the locking ground for relay E^3 .

Listening secretly ahead

55 It will appear presently from descriptions to follow, that in the event that a response is had from a local telephone as A' , called through the switch element Fig. 3, under which responded condition the back-bridge relay K^2 , and the relay J^3 will be energized, if the operator has the keys k^2 and e^2 both operated, this will not only open the energizing circuit for relay A^3 as before stated, but due to the back-bridge relay K^2 and relay J^3 being energized, the traced circuit to the re-

lease magnet will be open at the lower spring of relay J^3 , so that the operator may talk secretly with the party connected through the switch element Fig. 3, as against the party at telephone A.

70

Line leading to telephone A' assumed idle when selected

If it is now assumed that at the time the wipers 306 to 309 were set upon bank terminals 312 to 315 the line "21" is encountered idle, the bank terminal 315 will not constitute busy-ground, and in fact will have battery potential thereon, derived through the cut-off winding of the line switch B' in Fig. 3B. However, the latter is of no moment in the operation about to be described. There being no ground to energize the outside winding of the private magnet in Fig. 3 and the inside winding thereof having been deenergized by the retraction of spring 310 on relay C^3 , the armature of the private magnet will retract and thereby permit the side-switch wipers e^3 and f^3 to move into their third positions. Thus, ground applied through spring 243 of relay F^2 in Fig. 2 is applied over conductor 251, side-switch wiper e^3 , wiper 309, bank terminal 315, conductor 327 to the cut-off winding in line switch B' in Fig. 3B.

80

The presence of the line switch B' is not of particular consequence in this connection, however, the ground applied to conductor 327 is necessary to guard the line "21" against intrusion. At the same time that ground is thus applied to conductor 327, battery is applied through side-switch wiper f^3 , conductor 328, spring 252 on relay F^2 in Fig. 2, conductor 253 winding of relay H^3 in Fig. 3, side-switch wiper e^3 , conductor 251, spring 243, on relay F^2 in Fig. 2 to ground, the relay H^3 actuating to effect the seizure by the switch element Fig. 3.

90

Signaling the called telephone

Signal current can now be traced from the ringing generator through springs 329, 330, wiper 306, bank terminal 312, conductor 331, bell of telephone A' , conductor 332, bank terminal 313, wiper 307, springs 333, 334, inside winding of ring cut-off relay F^3 to battery. Ring cut-off relay F^3 will not operatively energize under this condition, but the bell at telephone A' will be rung in accordance with the applications of ringing current through the agency of interrupter relay R^2 . When the party at telephone A' responds, a conductive path is closed through the telephone, and this will cause the relay F^3 to actuate, disconnecting the signaling current and locking the latter said relay by spring 335 to off normal ground on conductor 323. This latter ground will also be applied through the lower winding of back-bridge relay K^2 , attracted springs 334, 333, wiper 307, bank terminal 313, through the telephone 130

100

110

115

120

125

130

A' and back through bank terminal 312, wiper 306, attracted springs 330, 329, upper winding of relay K³ to battery, the latter said relay actuating. Relay J³ will energize in an obvious local circuit of relay K³.

The operator may disconnect the dial Z² from the winding of relay A³ by restoring key k², which will cause relay D² to restore and relay J² to actuate from ground at key k² (and also on upper spring on relay L²) to connect through the trunk conductors 1 and 2 to conductors 324 and 289, respectively. The calling party at telephone A will now be in talking relation with the party at telephone A' over a path involving conductors 1 and 2, springs 206 and 207, springs 205 and 208, springs 204 and 209 of the jack j, springs 203, 210, make-before-break springs 202 and 211 on actuated relay H², make-before-break springs 212 and 201 on actuated relay J², conductors 324 and 239, condensers, springs 337 and 336. From spring 336 the connection is continued forward through springs 338, 329, 330, wiper 306 to bank terminal 312. And from spring 337 the connection is continued forward through springs 334, 333, wiper 307 to bank terminal 313. The windings of the back-bridge relay K³ thus are in series with called telephone A', and the windings of line relay A³ are in series with the calling telephone A, remembering that due to the actuation of relay H² in Fig. 2 the current traversing the calling telephone A is in the opposite direction to that which existed when trunk conductors 1-2 were seized by the switch B in Fig. 1.

Party at telephone A hangs up first

If the party at telephone A hangs up first, relays A³ and B³ will deactivate in sequence, but the release magnet in Fig. 3 will not be energized. If the party at telephone A' now hangs up, this will cause back-bridge relay K³ to deactivate, followed by relay J³, consistent with its slow-releasing characteristic. However, before relay J³ has had time to deactivate ground will be applied from spring 340 through spring 341 to actuate the relay P³. The ground from spring 340 will find its way to spring 342 on relay H³, conductor 343, winding of series relay C⁴ in Fig. 4, winding of vertical magnet, side-switch wiper f⁴ to battery, causing the wipers 403 to 406 of switch element Fig. 4 to step into alignment with the 1 level of bank terminals. At the time relay J³ deactuates, and remembering that relay P³ will remain actuated thereafter consistent with its slow releasing characteristic, a circuit path can now be traced from ground on spring 344, winding of relay D³, spring 345, upper off-normal spring, conductor 325, and over the traced path, including conductor 250, retracted spring 326 to the release magnet causing the wipers 306 to 309 to be restored. However,

the wipers 403 to 406 in Fig. 4 are now off-normal, and these will be restored to normal in the following manner: ground on off-normal spring in Fig. 4, retracted springs 407, 408, conductor 409, spring on relay D³, conductor 346, upper off-normal spring in Fig. 4, spring 410 to the release magnet which energizes to restore the latter said wipers.

Party at telephone A' passes call

If it is now assumed that in place of the party at telephone A' hanging up, he desires to pass the connection to telephone C', the telephone number of which is "31", so that the calling party at telephone A may thereafter converse with the party at telephone C' privately, or in a Y connection wherein the party at telephone A' will remain in as one branch of the Y, this will be accomplished in the following manner: The party at telephone A while holding his telephone off the switch hook will dial digits 3-1. Responsive to the sending of the first digit 3 from the dial at telephone A', back-bridge relay K³ will retract its armature three times, spring 340 applying ground through attracted springs 341, 342, conductor 343, winding of relay C⁴, winding of vertical magnet, side-switch wiper f⁴ to battery, the wipers 403 to 406 being thereby set into alignment with the 3 level of bank terminals. At the time relay C⁴ actuated and for the duration of the series, relay Q⁴ will be energized, as will the inside winding of the private magnet N⁴. Following the termination of the last impulse of the series the armature of the private magnet N⁴ will retract, permitting the side-switch wipers e⁴ and f⁴ to step into their second positions. Upon the next digit 1 being sent, ground applied through the winding of relay C⁴ will be applied through the winding of the rotary magnet, wiper f⁴ to battery, driving the wipers 403 to 406 in to the first set of bank terminals 411 to 414, respectively, three said terminals, 414, 412 and 411, leading over conductors to the line switch cut-off relay, not shown, and to telephone C' in Fig. 3B.

In view of what has been described in connection with Fig. 3 as to the testing, hunting and seizing operations, it is thought that due to the similarity of the circuits in Fig. 4 to those in Fig. 3 for performing their functions, it will not be necessary to a comprehensive understanding of the operation of the switch element Fig. 4 to detail these operations. Suffice it to say, that assuming that the line leading to telephone C' is idle when the wipers 403 to 406 are set upon bank terminals 411 to 414, the relay H⁴ will actuate to effect the seizure. It may, however, be stated that the battery applied through side-switch wiper f⁴ is in this case applied directly to the upper terminal of the winding

of relay H^4 in place of being looped back through a contact on relay F^2 in Fig. 2, and the same may be said with respect to applying ground directly to side-switch wiper e^4 and to the lower terminal of the winding of relay H^4 .

It may also be stated, in this connection, that the application of signaling current to the telephone C' will be the same as described 10 with reference to the switch element Fig. 3 when calling telephone A' . And further, the operation of the ring cut-off relay F^4 and the back-bridge relay K^4 , responsive to the party at telephone C' removing his receiver, will 15 correspond to the operation described with respect to relays F^3 and K^3 in Fig. 3 when the party at telephone A' removed his receiver.

It is pointed out here that the resistor connected to spring 338 and its make contact is for the purpose of increasing the obstruction of the back-bridge relay winding of an idle element, and this applies for the corresponding positioned resistor connected to the spring 415 on relay H^4 . It is noted that when the connection was made to telephone A' that the windings of back-bridge relay K^4 were in bridge of the talking connection, wherein the resistor 416 was in series with the upper 20 winding of relay K^4 .

The party at telephone A being assumed to still have his receiver off the hook when the party at telephone C' answers the call, it will be noted that the telephone C' is in a talking 35 branch of the Y connection between calling telephone A and telephones A' and C' , so that the three parties to the connection may converse mutually.

It is pointed out in this connection that the 40 relays L^3 and L^4 are provided to prevent dial impulses from being heard at the main exchange telephone when the call is being passed. For example, at the time that the party at telephone A' operated his dial to 45 pass the call to telephone C' , ground from the lower spring of relay C^4 was applied over conductor 417 to the winding of relay L^3 , causing it to actuate to disconnect the talking connection back towards telephone A at 50 springs 336 and 337. This relay L^3 is then locked over conductor 409, retracted springs 408, 407, to the lower off-normal spring in Fig. 4, and this locked condition of relay L^3 will endure starting from the first impulse 55 sent to the windings of the back-bridge relay K^3 until it is unlocked when relay H^4 in Fig. 4 actuates to effect the seizure of the switch element Fig. 4, or that the relay E^4 actuates 60 because of the switch element Fig. 4 encountering a busy barred called line condition. Relay L^4 operates and locks and unlocks in the same manner as described for relay L^3 .

In the event that the switch element Fig. 4 65 encountered a busy barred condition, the re-

lay E^4 will actuate in the same manner as described for relay E^3 in Fig. 3, wherein busy-tone from source T^4 will be applied through the lower springs on relay E^4 , lower springs on relay L^4 to conductor 324, and over the 70 previously traced busy-tone path, audible to the party at telephone A and also audible to the party at telephone A' .

Party at telephone A' hangs up first 75

The party at telephone A' may now withdraw from the Y connection by hanging up. This will cause relay K^3 to deactivate, followed by relay J^3 , relay P^3 actuating before relay J^3 deactivates and sustains until after 80 relay J^3 deactivates. A circuit path can now be traced from ground on retracted spring 344 on relay J^3 , winding of relay D^3 , spring 345, upper off-normal spring in Fig. 3, conductor 325, spring 249 on relay F^2 , conductor 85 250, spring 326 to the release magnet, the wipers of the switch element Fig. 3 restoring.

The party at telephone C' may now continue the conversation with the party at telephone A , and he may, if desired, pass the 90 call by means of the switch element Fig. 3 to any accessible telephone; in fact, if desired, back to telephone A' . However, it will be now assumed that the party at telephone C' desires to pass the call to telephone D' in Fig. 3B, the telephone number of which is "41". This will be accomplished in the following manner:

Party at telephone C' passes call to telephone D' 100

The party at telephone C' , while holding his telephone off the switchhook, will dial digits 4-1. Responsive to the sending of the first digit 4, back-bridge relay K^4 will retract 105 its armature four times, spring 423 applying ground through spring 424, conductor 425, winding of relay C^3 to the vertical magnet in Fig. 3, the latter said magnet operating to step the wipers 306 to 309 into alignment 110 with the 4 bank level, in the manner as when the said wipers in a previous description were caused to align with the 2 level, the side-switch wipers moving into their second positions. Responsive to the sending of the second digit 1, the wipers 306 to 309 will be 115 caused to rotate in to the first set of bank terminals 351 to 354, respectively. The switch element Fig. 3 will function as before when operated into connection with the line leading to telephone A' , wherein the relay H^3 will actuate, and signaling current will 120 be applied effective to the bell at telephone D' .

Upon the response at telephone D' , the 125 relays F^3 and K^3 will actuate, as when the response occurred at telephone A' . This will place the telephone D' in a Y connection with calling telephone A and telephone C' .

Restoring switch element in the event there is no response or if the line to which the connection is passed is encountered busy

If it is assumed that when the switch element in Fig. 3 effected connection to the terminals 351 to 354, the bank terminal 354 constituted busy-ground. This would cause the relay E³ to actuate and lock, and thus prevent the relay H³ from actuating, due to the fact that the side-switch wipers are restrained in their second positions. Under this condition, the passing party at telephone C' may desire to cause the wipers of the switch element Fig. 3 to become restored, so that they may be then reoperated, this time into connection with the terminals 312 to 315, corresponding to telephone A', for example. The restoration of the wipers would be accomplished as follows:

The party at telephone C' will send the digit 1, constituted of one open impulse. This will cause the relay K⁴ to retract its armature one time. Thus, a ground impulse will be sent from spring 423, through spring 424 to the winding of relay P⁴, the latter said relay actuating and sustaining in accordance with its characteristic. When relay K⁴ re-attracts its armature, a circuit can be traced from the winding of the release magnet in Fig. 3, spring 326, conductor 250, spring 249 on relay F² in Fig. 2, conductor 325, upper off-normal springs in Fig. 3, conductor 356, spring 430, upper spring on relay K⁴, springs 431, 408, 407 to off-normal ground in Fig. 4. The release magnet in Fig. 3 will thus operate to restore the corresponding wipers. In this connection it will be noted that if the switch element Fig. 3 had not encountered busy-ground, and had therefore seized the line of telephone D', but that the party at telephone D' failed to respond to the signaling, and the party at telephone C' then wished to restore the wipers 306 to 309, in order to call another telephone as A', the said restoration of the wipers would be accomplished in the same manner as last described when the line was encountered busy.

Had the switch element Fig. 4 been under a passing operation, in place of the switch element Fig. 3, in the last foregoing restoring operation, corresponding circuits would have come into play, only that conductors corresponding to 250 and 325 would not be present, as the connection from spring 410 to the off-normal spring is direct.

Ringing tone

It will be noted that when one of the switch elements Figs. 3 and 4 are applying signaling current to a called line, ringing induction through the corresponding ring-cut-off relay is applied audible to the party at telephone A. This ringing induction will also be heard by the party at a telephone

as A' or C' who may have passed the connection, since this telephone will be in talking relation to the circuit path leading back to telephone A.

Switches may be restored from main exchange if no response has been obtained from a telephone local to the private exchange

In the event that when the connection was made through the element Fig. 3 to the telephone A', in foregoing descriptions, the party at telephone A' failed to respond, the wipers of the latter said switch element may be restored by the party at telephone A hanging up his receiver. This will cause relay A³ in Fig. 3 to deactivate, followed by relay B³. A circuit can now be traced from grounded spring 302, off-normal spring, conductor 325, spring 249 on relay F² in Fig. 2, conductor 250, spring 326 to the release magnet, the latter said magnet operating.

It will be noted, in this connection, that should the party at telephone A', at the time of passing the connection to telephone C' through the agency of the switch element Fig. 4, hang up his telephone before the party at telephone C' responded, and party at telephone A thereafter hangs up, the wipers of the two switch elements Figs. 3 and 4 will restore in the following manner:

When the party at telephone A' hangs up, the relay K³ will deactivate, followed by the actuation of relay P³, and the deactivation of relay J³, in sequence. Then after relay J³ deactivates, and before relay P³ deactivates, a circuit path can be traced from grounded spring 344, winding of relay D³, spring 345, upper off-normal spring, conductor 325, spring 249 on relay F² in Fig. 2, conductor 250, spring 326 to the release magnet. The wipers of the element Fig. 3 will thus restore to normal. Then, when the party at telephone A thereafter hangs up and relays A³ and B³ deactivate, a circuit can be traced from grounded spring 302, conductor 346, off-normal springs in Fig. 4, spring 410 to the release magnet, the wipers in Fig. 4 restoring to normal.

Operator may pass call through the switch element in Fig. 3 by switch element Fig. 4

If it is assumed that at the time the operator sets the wipers of the switch element Fig. 3 onto the terminals of the line leading to telephone A', she failed to get a response, she could annex the number of another telephone as that of telephone C', which is "31", and thereby call that telephone. It is accomplished in the following manner:

When the digits 3-1 are annexed by the dial Z² in Fig. 2, the relay A³ in Fig. 3 will correspondingly operate. This will send ground impulses from spring 301, conductor 304, spring 241 on actuated relay K² in Fig.

2, conductor 242, attracted spring 305 on relay B³ in Fig. 3, attracted spring 342, conductor 343, winding of series relay C⁴ in Fig. 4 to the vertical magnet, the vertical magnet operating in accordance with the first digit 3, and the rotary magnet operating in accordance with the second digit 1. In fact, the switch element Fig. 4 will behave exactly as if the passing operation were directed from the telephone A', through the agency of the back-bridge relay K³, since the conductor 343 is common to both operations, and the passing, directed from telephone A', has been described.

15 It is noted in this connection that through the agency of spring 358 on relay E³, in the event that the operator perceived the busy-tone, when the busy line leading to telephone A' became selected by switch element Fig. 3, she could annex the number of an alternative telephone and thereby pass the call through the switch element Fig. 4, having in mind that the spring 342 will be retracted due to relay H³ not having energized, while spring 358 will be attracted. This will save the operator first restoring the wipers of the switch element Fig. 3, in the event a new call to another local telephone is to be made, under the condition that a response has not been obtained, or that the line first called is encountered busy.

20 It will be noted, in this connection, that under the last described operation, wherein the operator annexed a number, thereby operating the switch element Fig. 4, while the switch element Fig. 3 is still in connection with the line to telephone A', the wipers of the switch element Fig. 3 will be restored to normal responsive to the switch element Fig. 4 being set upon the terminals of the line to telephone C', and is accomplished in the following manner:

25 When the switch element in Fig. 4 is set upon the terminals of the line leading to telephone C', or any line, either the relay H⁴ will actuate to effect the seizure of the line, if idle, or the relay E⁴ will actuate because of encountering a busy condition. Thus, when either relay H⁴ or relay E⁴ actuates ground 30 from off-normal spring in Fig. 4 is applied through spring 431, upper spring on relay J⁴, spring 430, conductor 356, off-normal spring in Fig. 3, conductor 325, spring 249 on relay F² in Fig. 2, conductor 250, spring 326 35 to the release magnet, the wipers in Fig. 3 restoring to normal.

30 Further, in the event that there is no response at telephone C' reached by switch element Fig. 4, or that the line leading thereto is encountered busy by the switch element Fig. 4, the operator may further annex a number, as "41", and thereby again operate the wipers of the switch element Fig. 3, which became restored, and upon the wipers of the 40 latter said element being set upon the ter-

minals of a called line, the switch element Fig. 4 will be thereupon caused to restore its wipers to normal. This is accomplished in the following manner:

45 When the relay A³ operates in response to the dial Z², it will send impulses to the vertical magnet and then to the rotary magnet in Fig. 3. The impulse paths to these magnets are the same as existed when the operator first operated the switch element Fig. 3 into connection with the terminals of the line leading to telephone A', since the impulse path through the relay C⁴ is now open, due to the wipers in switch element Fig. 3 being at normal. However, upon the wipers of the switch element in Fig. 3 being set upon bank terminals, off-normal ground derived through spring 243 on relay F² in Fig. 2 will be applied either through spring 359 on relay E³ or spring 360 on relay H³ in Fig. 3, depending upon which relay E³ or H³ is actuated, springs 361, 362, 363, conductor 346, off-normal spring in Fig. 4, spring 410 to the release magnet, causing the wipers 403 to 406 to restore.

50 *Answering party in a passed call may restore antecedently operated switch element*

55 In previous descriptions, wherein a call is passed, a Y talking connection could exist wherein the calling telephone A is on one branch and the switch elements Figs. 3 and 4 each link a branch of the Y connection. By opening switch-arm 365 and closing switch-arms 366 and 367 in Fig. 3, and by opening switch-arm 435 and closing switch-arms 436 and 437, a new behavior is attained wherein a party answers a passed call, he incidentally automatically causes the other private branch exchange branch of the Y connection to be thereupon disconnected. This is accomplished as follows:

60 Let it be assumed that the call is passed by a telephone connected through the switch element Fig. 3, by the switch element Fig. 4, to another telephone. The relays K³ and J³ will be actuated, the relay J³ being energized through the make-before-break springs on relay J⁴ in Fig. 4. When the party at the telephone to which the call has been passed answers, the relay K⁴ will actuate, and this will apply ground from spring 423, switch-arm 436, attracted spring 326 to the release magnet in Fig. 3, causing the wipers 306 to 309 to be restored to normal, after which the relays K³ and J³ will deactuate, because the energizing circuit thereof has been opened by the restoration of the wipers. This ground from the spring 423 will now be applied over the circuit path involving the switch-arms 436 and 437 to the winding of relay J⁴, the latter said relay actuating, as when the switch-arm 435 was in its closed position.

65 The operation of releasing the switch element Fig. 4 will be the same as last described,

in the event that a call has been passed through the switch element Fig. 3, from a telephone connected through the switch element Fig. 4, upon the party last called answering. This adaptation or alternative use of the switch elements Figs. 3 and 4 is to insure that when a call is passed the party passing the call will be excluded from the talking connection when the response occurs, to prevent his overhearing, in the event that he has not before hung up to himself cause the restoration of the wipers of the switch element from his line.

Call initiated by the operator at the private exchange made to the main exchange

In previous descriptions, the call was assumed initiated at telephone A in the main exchange. Means are provided for initiating a call at the private exchange by the operator thereat. Under this condition, the operator will manipulate the key k^2 , which will cause the relay E^2 to actuate and connect the operator's telephone over an obvious path in bridge of the trunk conductors 1 and 2. The spring 255 on relay E^2 energizes the relays B^2 and V^2 , and the relay R^2 is then energized from spring 256 in a local circuit of relay B^2 . This places the winding of the polarized relay Q^2 in a bridge path of the trunk conductors 1 and 2, and includes the spring 260 in the path. Springs 203 and 210 are attracted and thus opens the conductive path to the make-before-break springs 202 and 211, and places the resistor 261 in bridge of the said springs 202 and 211. Thus, the winding of the relay Q^2 serves to close the circuit for operating the line switch in the main exchange, and the resistor 261 serves to close a circuit including the windings of the relay K^2 , the latter said relay actuating. The actuation of relay K^2 at this time causes the same circuit changes as described heretofore with reference to its actuation, excepting that the circuit for the call lamp 226 is open at the spring 262 on relay E^2 . The armature of relay Q^2 is now tilted counter-clockwise, causing the supervisory lamp 265 to glow and closes a locking circuit for relay V^2 . Ground applied from the armature of relay Q^2 through upper spring on relay V^2 serves to lock the relay B^2 in the event key k^2 is restored and relay E^2 thereupon deactuates.

The operator at the private exchange may now operate the dial Z^2 to directly extend the connection from the trunk line conductors 1 and 2 to the called telephone B'' , the telephone number of which is "26451". At the time the winding of relay Q^2 is connected in bridge of the trunk conductors the line switch LS in Fig. 1 will thereupon seize first selector C'' . Responsive to sending the digits 2-6-4-5-1 the first selector C'' , the second selector D'' , the third selector E'' , and the connector F'' will operate in the well

known manner for switches of the stated type to extend the connection to the telephone B'' .

Upon the dial Z^2 being set for each digit the dial off-normal springs 264 will close a circuit from ground lower spring of relay E^2 to the winding of relay A^2 , the relay A^2 thus being energized for all off-normal positions of the dial Z^2 . So that as the dial finger-hold plate restores, and the dial impulse contacts are operating, a circuit can be traced from the dial contacts to attracted springs 208 and 205, wherein the spring 235 is in series. That is, the dial impulse contacts are now in a series path with the trunk conductors 1 and 2, having in mind that when the finger-hold plate of the dial restores to normal at the termination of each digit series the opening of springs 264 causes relay A^2 to deenergize and restore the winding of relay Q^2 in bridge of the trunk conductors 1 and 2, it being obvious that when the relay A^2 actuates it substitutes the dial contacts for the winding of relay Q^2 in bridge of the trunk conductors.

In view of previous descriptions, when the party at telephone B'' responds, the direction of current projected back from the front bridge or line relay of the connector F'' which energizes the relay Q^2 will be reversed, so that the armature of the relay Q^2 will now be tilted clockwise. This will extinguish the lamp 265, while maintaining the relays B^2 and R^2 actuated, regardless of relay E^2 . But if relay E^2 deactuates while the armature of relay Q^2 is tilted clockwise relay V^2 will unlock, and relay B^2 will sustain actuated and come under the control of relay Q^2 . The operator may, if desired, converse with the called party at telephone B'' , instruct him to wait, and thereafter restore the key k^2 , the relay E^2 deactuating, leaving relay B^2 locked to the armature of relay Q^2 .

Extending portion of call made to telephone B'' in opposite direction to local telephone to complete same

The operator may now extend a connection to a desired local telephone, such as A' for example, in the manner before described, that is, by manipulating key k^2 to cause the actuation of relay D^2 , L^2 and H^2 . It is noted that while relay H^2 reverses the connection between springs 203-210 and the windings of the relay K^2 , this is of no moment due to the said springs being attracted. The impulse contacts of the dial Z^2 is now in series between ground at spring 235 and the upper winding of relay A^2 in Fig. 3. It will not be necessary to re-detail the operation of the circuit in Figs. 3 and 4 in effecting connection to a local telephone under direction of the dial Z^2 . Suffice it to say, that after the desired local telephone has been connected to

and the party thereat perhaps having responded and talked with the operator, the operator will restore the key k^2 whereupon relays D^2 and L^2 will deactuate, while relay H^2 will remain locked to conductor 219. 5 Ground applied through the contact of key k^2 will now be applied through attracted spring 224 to energize relay J^2 . The actuation of relay J^2 disconnects the windings of relay K^2 and substitutes conductors 239-324, which are the talking conductors leading towards the called local telephone, it being noted that the windings of relay A^2 in Fig. 3 are in bridge of the latter said conductors, 10 energized through an obvious path including the resistor 261 and the lower spring on relay B^2 . The party at telephone B'' in Fig. 1 is now in talking relation with the party called through one of the switch elements 15 Figs. 3 or 4, and this party may be assumed to be at telephone A' . The talking path is joined inductively by the condensers normally short circuited by the springs 203 and 210, respectively, wherein the winding of relay Q^2 is in bridge of the section extending to telephone B'' , and the resistor 261 including lower spring on relay B^2 , is in bridge of the section extending to telephone A' .

Then the party at telephone A' may hang 30 up and restore the switch element which connected to his line in the manner before described, but the line relay A^3 in Fig. 3 will remain energized under control of the party at telephone B'' , since relays B^2 and R^2 are 35 under control of the relay Q^2 .

Upon the party at telephone B'' hanging up, the direction of current traversing the winding of relay Q^2 will be reversed, causing the armature of the latter said relay to tilt counter-clockwise and cause the lamp 265 to 40 re-glow. Under this condition the relay B^2 will become unlocked and its dependent relay R^2 will reactuate, removing the winding of relay Q^2 from its bridge relation to the trunk and also removing the resistor 261 from its bridge relation at the time relay B^2 deactuates, and before relay R^2 has had time to 45 deactuate. The switches in the main exchange will restore to normal, and relays B^2 and R^2 are slow releasing, and relay R^2 sustains long enough to hold open the circuit 50 energizing the line relay A^3 at lower spring on relay B^2 so that relay B^2 will deactuate. When relays A^3 and B^3 deactuate, it will 55 remove ground from conductors 219 and 240 causing relay H^2 to unlock and relay J^2 to deactuate, whereupon the circuits involved in the call are in normal condition.

It will be understood from operations 50 previously described that in the call last made the telephone A' could pass the call, and it may be subsequently again passed as many times as desired as in the descriptions wherein the call originated at telephone A . 55 The breaking down of the connection in the

main exchange is under the control of the telephone B'' called in the main exchange, wherein it causes the winding of relay Q^2 to be first removed from its bridge connection, and consequently thereto opens the energizing path for relay A^2 . 70

Operator may extend connection by means of switching plug

An alternative way in which the private exchange operator may extend a connection over the trunk 1-2 is through the agency of the switching plug as shown in Fig. 11, for example. When the plug A^{11} is inserted into the jack j , ground from jack auxiliary spring 267 will be applied to conductor 219. Spring 268 will close the winding of relay Q^2 in bridge of the talking conductors of plug A^{11} , lamp 265 glowing, due to armature of relay Q^2 tilting counter clockwise. Operating key F^{11} applies ground from spring of key F^{11} over ring of plug A^{11} to energize relay A^2 . The actuation of relay A^2 places the contact of the dial Z^2 in bridge of the trunk 1-2, so that the telephone B'' may be called as before described, using the dial Z^2 , but not now employing certain circuits such as controlled by the key k^2 . When the party at telephone B'' responds, the direction of current in the trunk will be reversed so that the operator 95 may withdraw the plug A^{11} from jack and thereby have the windings of relay K^2 energized in series with the windings of the line relay in connector F'' , having in mind that the battery is normally connected to the 100 proper winding of relay K^2 to insure that it will not be energized in series with the winding of the line relay of line switch LS in Fig. 1. That is, battery will be applied opposing 105 battery at opposite ends with respect to trunk conductor 1, and also with respect to the windings of the line relay of the connector F'' , under the condition that the back-bridge relay thereof is not energized. Thus, the call 110 is now (with the back-bridge relay in connector F'' energized because of the responded condition at telephone B'') to all intents and purposes so far as the operator's private exchange switchboard is concerned the same as had a call been initiated at telephone A and directly extended therefrom to the trunk 1-2 referred to in previous description wherein relay K^2 energized. It is noted that relay B^2 has not energized. This is having 115 in mind that under the latter condition the circuit is wholly energized from the windings of relay K^2 .

Call may be made from a local telephone of the private exchange through a selector-connector direct to the trunk 1-2

The switch Q^8 in Fig. 8 is a selector-connector in some respects as has been used for local connections within a private exchange and for extending outgoing calls. It is, in 130

fact pointed out that with the exception of the wiper 802 of the present invention (of the set 801 to 804) and the circuits co-operative with this wiper, which includes the "1" and "0" levels, this switch is well known in the art and was so before the parent application hereof was filed.

Party at local telephone can dial "11" and energize call lamp individual to said telephone

It is noted that a jack j^s in Fig. 8 is introduced into the line leading to local telephone T^s . This jack is associated with the wiper 802 and comprises a part of the means provided by the present invention whereby the subscriber at telephone T^s may dial the number "11" and thereby cause a calling lamp 812 to glow to attract the attention of the operator.

The lamp 812 is individual to the line leading to telephone T^s and the jack j^s . So that when the operator notes the glowing of the lamp 812 she will understand that the party at telephone T^s is calling her, whereupon an ordinary operator's switching plug, or a switching plug as B^{11} shown in Fig. 11, may be inserted into the jack j^s , and key F^{11} operated to energize relay C^{11} , enabling the operator to communicate directly and secretly over the line leading to telephone T^s . It will thus be understood that each local line desired will have a jack corresponding to j^s and a call lamp corresponding to 812 individual to the respective said local lines to enable the party on any said local line to signal the operator with a lamp individual to his line, and he will cause said lamp to glow by removing the receiver and dialing the number "11" to set the wipers of the switch like Q^s on bank terminal set "11".

In addition to the call lamp feature individual to the line, a means involving a relay 813, adapted to be connected with the wiper 802 is employed. The winding of this relay may be low or high depending upon whether the corresponding local line is to be barred or allowed access to the trunks, such as 1-2, leading to the main exchange. That is, through the agency of this relay 813 it is possible to restrict any telephone against calling into the main exchange. This relay 813 also serves for calling in the operator by the call lamp 812, as referred to.

If it is assumed that the party at telephone T^s desires to call in the operator he will remove the receiver, thereby closing an obvious circuit path to energize the line switch line relay 815. This will cause the line switch LS^s to plunge-in and extend the connection to conductors 816-817 leading in to the switch Q^s . A circuit can now be traced including the windings of relay A^s and the

telephone T^s . Relay B^s will energize in a local circuit of relay A^s , applying ground from spring 818 over release trunk conductor 819 to the busy lamp 820. This ground is also extended through jack spring 821 to private normal conductor 806 to guard the line against intrusion. The busy lamp 820 will serve to guard the jack j^s .

The party at telephone T^s will now send the first digit 1 which will cause the armature of relay A^s to momentarily retract and send a ground impulse through series relay C^s to the vertical magnet, stepping the wipers into alignment with the 1 level of bank terminals. The private magnet K^s is also energized (by grounded spring on relay C^s) with the vertical magnet, so that following the one impulse, the side-switch wipers 823 and 824 will move into their second positions. Upon the second digit 1 being sent the relay A^s will send a ground impulse through winding of relay C^s to the rotary magnet, causing wipers 801 to 804 to be stepped in to the first set of bank terminals 825 to 828, and the private magnet K^s to energize in a local circuit of relay C^s . Bank terminal 826 is permanently grounded, while the remaining bank terminals of the set 825 to 828 are unconnected, as is shown in Fig. 8B. Relay 813 will energize from ground on bank terminal 826, wiper 802 to the winding of relay 813. A circuit can now be traced from grounded conductor 819, springs of line switch, contacts of relay 813 to the call lamp 812. Upon the operator noting the glowing of lamp 812 she can respond thereto by inserting plug B^{11} of the cord pair shown in Fig. 11 into jack j^s , and then manipulate the listening key G^{11} , and key F^{11} in order to energize relay C^{11} . The spring 821 will flex to the grounded spring to maintain conductor 806 grounded, and the talking springs of the jack j^s will be flexed from their resting contacts to open the energizing path for the relay A^s . Relays A^s and B^s will de-actuate in sequence, and a circuit path may be traced from the grounded spring 830, spring 831, off-normal spring to the release magnet, the wipers being thereby restored and ground will at the same time have been removed from conductor 819, permitting the line switch to deactuate, whereby the switch Q^s is subject to new use. The lamps 812 and 820 will now be extinguished, and the line leading to telephone T^s will be guarded against intrusion due to the ground on conductor 806.

If it is assumed that the relay 832 in Fig. 8A is substituted for the relay 813, the same operation as described in respect to relay 813 will ensue. However, in the circuit operation about to be described there will be a difference depending upon which relay 813 or 832 is employed.

Making a call from telephone T^s to the trunk line leading to the main exchange

If it is assumed that the party at telephone T^s desires to make a call to the main exchange over one of the trunks 1-2, reached from the 0 level of switch Q^s , the operation will be as follows: The party at telephone T^s will operate his dial in accordance with the digit 0, causing the relay A^s to momentarily retract its armature 10 times. This will cause the vertical magnet to step the wipers into alignment with the 0 level of bank terminals. Off-normal springs 834 and 835 will operate from the shaft cam, not shown, it being noted that the said off-normal springs 835 first operated when the shaft attained the 9 level. Relay H^s is now actuated and the side-switch wipers move into their second positions. Ground can now be traced from the spring on relay E^s , spring on relay H^s , to the rotary magnet, the rotary magnet operating to step the wipers 801 to 804 in to bank terminals 836 to 839, corresponding to the trunk 1-2.

Fig. 8C shows the terminal arrangement cooperative with the talking wipers 803 and 804, private wiper 801 and auxiliary wiper 802 of the 0 level. Thus the wipers 803 and 804 have access to the talking conductors of trunks on the first nine positions, and the wiper 803 will receive busy-tone when it moves to the tenth position. The wiper 801 will have access to the private conductors companion to the last referred to talking conductors on the first nine positions, respectively. The wiper 802 will have access to the winding of the relay 840 at each one of the nine positions. That is, there will be capacity for nine trunks leading out from the 0 level to the main exchange.

Any desired local line can be barred from connecting to a main exchange trunk

In the operation about to be described it will be assumed that the relay 813 is in a circuit as shown, and it is stated that this relay is of relatively low resistance, and relay 840 is marginally adjusted so that when the winding of relay 840 is connected in series with the relay 813, as will appear presently, relay 840 will derive enough current to operate, but relay 813 will not derive enough current to operate. It will thus be clear that when wiper 802 engages any bank terminal on the 0 level corresponding to a trunk it will place the windings of the relays 813 and 840 in series wherein relay 840 will operate to place a false busy-ground on wiper 801, so that the switch Q^s will behave as if all the private bank terminals of the 0 level were busy-grounded. Thus, the wipers will rotate on to the tenth position where wiper 803 will receive busy-tone audible to the party at telephone T^s , indicating to him that his line

is barred against calling into the main exchange. Had the high resistance winding relay 832 shown in Fig. 8A been substituted for relay 813 in the particular line leading to telephone T^s , relay 840 would not derive enough current to operate it and it therefore would not place a false ground on wiper 801 and therefore the wiper 801 would hunt for and seize the first idle trunk. Relay 832 will not now operate, due to its marginal adjustment.

Operation of connector-selector Q^s

Going back to the condition wherein the wipers 801 to 804 were stepped to the first set of bank terminals of the 0 level wherein relay 813 is employed in place of relay 832, if it is assumed that bank terminal 836 has busy-ground this ground will be communicated to the winding of the private magnet K^s , the latter said magnet actuating. The private magnet K^s will remain actuated as long as the wiper 801 receives ground from a bank terminal, and when it fails to receive ground the private magnet will deactivate and permit the side-switch wipers to move into their third positions, disabling the rotary magnet. It is noted that as long as the side-switch wiper 824 remains in its second position the relay E^s will interrupt the circuit to the rotary magnet, to keep advancing the wipers until the wiper 801 fails to receive ground, and thus permits the side-switch wipers to move into their third position, at which time a circuit may be traced from grounded conductor 819, springs on the private magnet, inner winding of the relay L^s , side-switch wiper 824, wiper 801, conductor 223, springs on relay P^2 in Fig. 2, winding of cut-off relay O^2 to battery, the relays L^s and O^s actuating. The outer winding of relay L^s will lock to the conductor 819, and the ground received from conductor 819 will traverse the off-normal contacts 834, energizing the relay D^s , closing the conductors 816-817 to the wipers 803-804.

If it is assumed that the first bank terminal encountered by the wiper 801 constituted battery potential in place of ground potential, the set of bank terminals 836 to 838 will be seized, the talking path from telephone T^s being completed in a series path over trunk conductors 1-2, operating the line relay L^s in Fig. 1 to extend the connection to first selector C'' . The party at telephone T^s may now annex digits by his dial to direct the call through the switches to telephone B'' or any other telephone tributary to the main exchange.

It is noted that the shunted series relay M^s will be energized in series with the trunk conductors 1-2, and its grounded spring will energize the release relay B^s to maintain ground on conductor 819, after the relay A^s

becomes deenergized resultant to the actuation of the relay D^s.

If the party at telephone T^s hangs up, the relay M^s will deactivate, followed by the relay B^s, whereupon the previously traced circuit for the release magnet will be closed to restore the wipers.

The switch Q^s will operate as a connector on levels below the 9 level, and under this condition when the wipers are stepped to align with the desired level below the 9 level, the rotary magnet will not thereupon operate, and is only subject to operation by directive control from the dial. Under such condition the relay H^s will not be energized, so that when the private magnet K^s retracts and the side-switch wipers move to their second positions the rotary magnet becomes under the control of relay A^s. When the second series of impulses operates relay A^s, corresponding ground impulses will be sent through the winding of relay C^s lower contact of relay H^s to the rotary magnet, the wipers stepping in correspondingly. The private magnet is held operated from the grounded spring on relay C^s during the time the wipers are being stepped in, so that when the relay C^s retracts its armature and the private magnet retracts, the side-switch wipers will move into their third positions. If ground potential is found by the wiper 801 on the bank terminal upon which it is resting, the relay L^s will not actuate, energized by its inner winding and locked by its outside winding to conductor 819 as would be the case if wiper 801 is deriving battery potential. Under this condition of relay L^s not actuating, ground from conductor 819 traverses the lower spring of relay L^s, side-switch wiper 822, winding of relay C^s, outside winding of relay A^s, side-switch wiper 823 to battery. Busy-tone is applied from source T', upper contact of relay C^s to the lower talking conductor, audible to the party at telephone T^s. The calling party may now hang up and cause the restoration of the wipers of the switch in the manner before described.

Assume that the wipers 801 to 804 were set upon bank terminals 841 to 844 by directly operating the switch Q^s in accordance with the digits 4-1, and further assume that Fig. 3B is placed above Fig. 8 so that the conductors corresponding to telephones C' and B' register with the middle two sets of three conductors on Fig. 8. The latter has in mind that the switch Q^s in a private exchange would have common access to the same local telephones as the switch elements Figs. 3 and 4.

Signaling current from source G^s will now be applied through contacts on ring cut-off relay F^s, contacts on relay D^s, contacts on relay L^s, wiper 804, bank terminal 844, telephone D', bank terminal 843, wiper 803, con-

tacts on relays D^s, L^s, D^s, F^s, winding of the latter said relay to battery. Upon the party at telephone B' removing his receiver, relay F^s will energize over the conductive path established and actuate and lock by its outside winding, the back bridge retardation coil J^s incidentally energizing in series with telephone D'. The calling party at telephone T^s and the called party at telephone D' are now in talking relation. The restoration of the wipers of the switch Q^s is under control of the party at telephone T^s.

It will be noted that when the wipers of the switch Q^s are operated into alignment with the 9 level whereat the springs 834 are open and the springs 835 are closed, the rotary magnet will thereupon automatically operate so that the wiper 801 will hunt for an idle trunk, and seize the first one encountered, in the manner as when operating on the 0 level. However, since the relay G^s is not operated the trunk seized will be signaled upon as if a local telephone as D' had been called. The only difference being that the rotary movement of the wipers was automatic as a hunting operation in place of entirely directive as when calling telephone D'. The telephone C' reached over the first set of terminals of the 3 level may also be assumed as also reached by way of the first set of bank terminals 845 to 848 of the 9 level. The sets of bank terminals in Fig. 8 shown co-operative with wipers 801 to 804 are assumed to be the first sets. They concern the 1, 2, 3, 4, 9 and 0 levels counting from the bottom.

Setting the circuits in Figs. 2, 3 and 4 for night service

A salient feature of the present invention, is the means for setting up night connections, so the trunk 1-2 may be potentially extended to or pre-set with respect to any desired local telephone line through the agency of the switch element Fig. 3. Means are also provided for causing the switch element Fig. 3 to seize the pre-selected local line responsive to the trunk 1-2 being seized from the main exchange. The local line will be thereupon signaled upon. The party on the local line selected, after responding, may pass the call to another local line through the agency of the switch element Fig. 4.

When the party in the main exchange who has made a call to a pre-selected local line hangs up, the switch element Fig. 3 will unseize, but not restore its wipers. The switch element Fig. 4, however, will restore its wipers if used in a passing operation.

If the trunk is seized at the main exchange end after its switch element Fig. 3 has been pre-set upon the terminals of a desired local line, and the key e² left operated, and the key k² restored, a busy-tone will be applied audible to the calling party in the main exchange, while at the same time dis-

abling the relay H^3 in Fig. 3 from energizing, if in the meantime after pre-setting the switch element Fig. 3 and the time when the trunk was seized at the main exchange, the pre-set local line becomes busy by the party thereon initiating a call, or the local line has been seized by an accessible switch.

It is noted that the party on the pre-selected local line may, under the condition, have made an outgoing call to the main exchange, perhaps selecting the trunk line 1-2 pre-set with respect to his line, or some other trunk, or perhaps has made a local call employing the switch Q^8 , as any of these operations will cause the pre-selected local line to become busy-guarded by ground on its private-normal conductor.

The private automatic exchange operator, in effecting a setting for night service, will manipulate the key e^2 into its operated position, which will energize relay F^2 . This will open the path traced from the terminal engaged by the side-switch wiper f^3 , to the upper terminal of the windig of relay H^3 , when wiper f^3 is in its third position. It will also open the path to ground traced from the terminal engaged by the side-switch wiper e^3 when in its third position, and connect the latter said terminal to the lower terminal of the winding of relay S^2 . The conductor 270 is connected to the winding of relay H^2 . The conductor 250 is opened at spring 249 to disable the energization of the release magnet in Fig. 3.

The operator may now manipulate key k^2 into its operated position, leaving key e^2 operated, and then operate the dial Z^2 in the manner before described, to thus operate the switch element Fig. 3 into selective relation to any desired local line, as A' in Fig. 3B, by sending digits 2-1. However, when the side-switch wipers f^3 and e^3 move into their third positions, the relay H^3 will not energize to apply signaling current to the selected line. It will be noted, however, that if the selected line is busy, the operator will perceive the busy tone and the side-switch wipers will not pass into the third positions.

This latter would not occur if the conductor extending from the terminal engaged by the side-switch wiper e^3 when in second position were looped through a set of normally closed contacts on relay F^2 in Fig. 2, and under the latter condition the side-switch wipers would move into their third positions. However, as shown, the busy-ground received by the wiper 309 will be applied over conductor 251 to energize the relay S^2 , which will apply busy-tone from conductor 401 to trunk talking conductor 2, and also audible to the operator. The operator will now restore the key k^2 , leaving key e^2 operated for the duration of the night service arrangement.

If the local line pre-selected by the switch

element Fig. 3, under the condition that relay F^2 is energized and key k^2 is restored, becomes busy, perhaps in making a local or main exchange call, or it has been seized, and conductor 251 leading to wiper 309 thereupon becomes grounded, the relay S^2 will actuate to disable relay N^2 from energizing.

If the trunk 1-2 is now seized at the main exchange, the relay K^2 will energize in a series path including the trunk conductors 1-2. The calling party will perceive the busy tone applied by way of the lower spring of relay K^2 over the trunk. The lamps 220 and 226 will glow responsive to the actuation of relay K^2 , and the ground thus applied through spring 217 to conductor 219 will operate relay P^2 to make the trunk 1-2 busy to switches as Q^8 at the private exchange end. It is noted, however, that even if no busy tone were applied to the trunk through the lower spring of relay K^2 , the absence of ringing induction due to the fact that relay H^3 does not energize and apply signaling current to the now busy local line pre-selected, will serve to apprise the calling party of the fact that the pre-selected local telephone line is busy and that the trunk therefore cannot be used for a call from the main exchange to any local line of the private exchange, including the pre-selected line.

Call from main exchange over trunk 1-2 under the condition that the preselected local line is idle

Under the condition of the pre-selected local line being idle at the time the trunk 1-2 is seized from the main exchange, wherein the relay K^2 will thereupon actuate and cause lamps 220 and 226 to glow, spring 241 closes the path from the resting contact of spring 301 on relay A^3 to the spring 305 on relay B^3 . Ground on the upper spring on relay S^2 is applied through attracted upper inside spring on relay K^2 , make-before-break spring and winding of relay N^2 , spring 252 on relay F^2 , conductor 328, side-switch wiper f^3 to battery, the relay N^2 actuating and locking to conductor 219. Relay J^2 will energize in a local circuit of relay N^2 , to disconnect the windings of relay K^2 and connect the conductors 239-324 to trunk conductors 1-2, so that the windings of relay A^3 will energize from the calling telephone over the trunk. The lower spring on relay N^2 will maintain the closed circuit traced from the resting contact of spring 301 to the spring 305. The relay B^3 is now energized. Ground from spring on relay N^2 is applied to conductor 323. Ground from spring on relay N^2 is applied to conductor 251. Battery from spring on relay N^2 is applied to conductor 253. Relay H^3 will thus energize to effect the seizure of the pre-selected local line, its private normal conductor having been pre-

viously busy-guarded when relay N^2 first caused conductor 251 to become grounded.

The pre-selected line will be signaled upon from the signaling current generator in Fig. 3, and the relay F^3 will actuate when a response occurs on the local line, and the back-bridge relay K^3 will thereupon energize, followed by relay J^3 energizing in a local circuit of relay K^3 . Conductor 270 will receive ground from spring 344, which will cause relay H^2 to actuate to reciprocate the relationship of the trunk conductors 1-2 with respect to the windings of relay A^3 , so that the current traversing the calling telephone will be reversed in direction. Thus, the pre-selected local telephone will be signaled as if the switch element Fig. 3 had been directionally set upon the local line at the time, in place of having been pre-selected.

If the local party hangs up first, deenergizing relay K^3 , the relay H^2 will deactivate and restore the direction of current traversing the calling telephone to that existing when the call was initiated.

If the party calling through the main exchange to the trunk 1-2 hangs up after the local party, or before, the relays A^3 and B^3 will deactivate. Ground applied over conductor 346 from spring 302 will cause the wipers of the switch element Fig. 4 to restore to normal, since the latter said switch element will falsely step off-normal when the relay A^3 deactuated. The ground is removed from conductor 219 by the retraction of spring 305, so that relay N^2 will unlock, followed by the deactuation of relay J^2 , relay H^2 deactuating responsive to the back-bridge relay K^3 deactuating, thus causing the ground to be removed from conductor 270. The relay K^3 will deactivate either responsive to the local party hanging up or to the relay H^2 deactuating, so relay H^2 will deactivate responsive to the first party to the connection hanging up.

45 Local party can pass call

If when the local party responded, it was found that another local party was wanted, the answering local party may thereupon dial the desired local number and pass the call in the manner as when calls were passed in previous descriptions, as by operating the dial at telephone A' . This will operate the wipers of switch element Fig. 4 into connection with the desired line. The relay H^2 will be under control of the back-bridge relay K^4 over conductor 270, if the party at the pre-selected telephone hangs up. The party at the pre-selected telephone may hang up any time, but the switch element Fig. 3 will not restore its wipers, and relay H^2 will not deactivate until the party calling through the main exchange abandons the call, whereupon the switch element Fig. 4 will restore by rea-

son of ground being applied over conductor 346 from spring 302.

It is thus seen that the trunk 1-2 may be seized under the condition of the switch element Fig. 3 being pre-set upon a desired local line and then disabled as to restoring its wipers by operating key e^2 , as often as desired while remaining pre-set. And, each time the trunk is seized at the main exchange end signaling current will be applied to the pre-selected line consequent to the actuation of the relay H^2 responsive to the relay K^2 actuating. The signaling current is then cut off by relay F^3 when a response occurs on the local line. The response on the local line will also cause the actuation of the back-bridge relay K^3 , and this will in turn cause the reversing relay H^2 to actuate. The hanging up of the receiver on the local line will cause relay H^2 to deactivate to restore the direction of current projected back over the trunk, and this deactuation of relay H^2 will occur responsive to the party in the main exchange hanging up to deactivate relay K^2 which will cause the relay H^3 to deactivate to open the energizing circuit for the relay K^3 .

Call from telephone A in Fig. 1 over trunk conductors 3 and 4 to the operator's switch-board in Fig. 7

With reference to diagram Fig. 23, the party at telephone A will initiate a call and operate the calling device in accordance with the numerical position of the trunk line 100 3-4 leading to Fig. 5. This will complete a connection from telephone A through switches B and D to trunk line conductors 3-4 shown in Figs. 1 and 5 with legs to Fig. 6. A circuit can now be traced from battery upper winding of relay A^5 in Fig. 5, make-before-break spring on relay R^5 , conductor 3, telephone A, conductor 4, make-before-break spring on relay R^5 , lower winding of relay A^5 to battery, the relay A^5 110 actuating. Relay B^5 will energize in a local circuit of relay A^5 , applying ground to release trunk conductor 501 and conductor 502. A path can now be traced from ground on conductor 502, contact on relay S^5 , contact on relay T^5 , to the winding of relay P^5 , the latter said relay actuating. Having in mind that relays A^5 and B^5 are actuated, a circuit can now be traced from grounded spring on relay P^5 , lower spring on relay B^5 , winding of series relay C^5 , winding of vertical magnet, side-switch wiper 505 to battery, the relay C^5 and the vertical magnet operating to step the wipers 506 to 509 120 one step into alignment with the 1 bank 125 level. When the wipers step off-normal, the off-normal springs are operated so that off-normal ground is applied through the lower spring on relay P^5 to the winding of relay T^5 , the latter said relay actuating to dis- 130

connect the winding of relay P^5 . Relay P^5 will deactivate consistent with its slow releasing characteristic and open the circuit to the vertical magnet.

At the time the relay C^5 actuated it energized interrupter relay D^5 , and also the inside winding of the private magnet 510, so that when the relay C^5 deactuates responsive to the deactuation of relay P^5 , the side-switch wipers 505 and 512 will move into their second positions by reason of the private magnet retracting. When relay P^5 deactuates it will open the circuit energizing the relay T^5 , so that when relay T^5 deactuates the before described circuit for energizing the relay P^5 will become reestablished. Ground from spring on relay T^5 will now be applied through the winding of relay C^5 operatively effective thereto as before, but due to the position of the side-switch wipers will traverse the upper inside spring on relay E^5 , winding of the rotary magnet, side-switch wiper to battery, the rotary magnet operating to step the wipers 506 to 509 in one step to bank terminals 513 to 516. The private magnet operated responsive to relay C^5 , and when the latter relay deactuates the side-switch wipers may move into their third positions, and will, if the outside winding of the private magnet does not become energized from busy-ground found by wiper 507 on bank terminal 514. Assuming for the moment that busy-ground was not found by wiper 507, the private magnet will deactivate, and with the side-switch wipers now in their third positions, a circuit can now be traced from battery, side-switch wiper 505, lower winding of relay S^5 to ground, the relay S^5 actuating and locking by its upper winding to conductor 502. Relay T^5 already actuated from off-normal ground to deenergize the winding of relay P^5 before the side-switch wipers moved into their third positions, so that the actuation of relay S^5 precludes relay P^5 being again energized when relay T^5 deactuates.

It is thus seen that when the trunk 3-4 is seized the switch element Fig. 5 will be thereupon caused to select the first set of bank terminals of the 1 level responsive to a vertical and a rotary movement. The switch elements Figs. 5 and 6 are group-selecting and have circuits for carrying out this group selecting function which correspond to the circuits in the switch elements shown in Figs. 3 and 4. Fig. 5A on the sheet with Fig. 5 shows an exemplary arrangement of bank terminals co-operative with the wipers 506 and 507 of a group of three lines, it being noted that the last pair of said terminals in Fig. 5A are tied together, and this latter is to communicate busy-ground to the last terminal of the group co-operative with the stop wiper 506, in the event that the companion

bank terminal is busy-grounded. That is, when the private wiper 507 encounters busy-ground the private magnet will be kept energized so that when relay D^5 deactuates, ground from spring on relay C^5 will traverse contacts on relay D^5 , contacts on the private magnet, upper inside contact on relay E^5 to the rotary magnet to cause the rotary magnet to step the wipers ahead, at the same time applying ground through the contact of the rotary magnet to energize the relay D^5 and the inner winding of the private magnet. The actuation of relay D^5 will interrupt the circuit to the rotary magnet and cause it to retract its armature, whereupon the circuit will be again established to the rotary magnet, further stepping the wipers until a non-grounded terminal is encountered by wiper 507, so that the outside winding of the private magnet will become deenergized to permit the side-switch wipers to move into their third positions, or that the stop wiper 506 finds busy-ground on the last terminal of a group, at which time this ground will be applied through contact 520, make-before-break springs on relay E^5 , upper contact on relay C^5 , winding of busy relay E^5 , side-switch wiper 505 in second position to battery, the relay E^5 actuating and locking to off-normal ground. Tone from source TT₅ will now be applied through lower springs on relays E^5 and H^5 , conductor 4, telephone A, conductor 3, upper winding of relay A^5 to grounded battery, the calling party thus being apprised that all of the lines of the group are busy.

It will be understood that the lines may be in groups of any number from 1 to 10, or the number of terminals in a level, and where there is only one line in the group the contacts of the line co-operative with the wipers 506 and 507 will be tied, so that if this line is busy when selected the wipers will not be able to automatically move off, but on the other hand will cause the switch element to now lock-on-busy and the busy-tone applied audible to the calling party. And it will appear later that this busy-tone would also be audible to a party who may be connected through the switch element Fig. 6.

Going back to the condition wherein the wipers selected the first set of bank terminals of the 1 level, it will be clear that if the corresponding line is busy, the rotary magnet will automatically operate so that the idle line will be hunted for. There may be one or more lines in the group having the first line of the 1 level.

Operation of operator's trunk circuit in Fig. 7

Placing the sheet containing Fig. 7 above Fig. 5 so that the lines extending toward the margins register, and assuming that the wipers 506 to 509 have been set upon bank

- terminals 513 to 516 a circuit path may be traced from the ringing generator, springs 521, 522, wiper 508, bank terminal 515, conductor 523, spring on dial key M⁷ in Fig. 7, condenser 701, upper winding of relay F⁷, upper spring on relay E⁷, spring of key M⁷, line conductor 702, bank terminal 516, wiper 509, spring 525, lower spring and winding of ring-cut-off relay F⁶ to grounded battery. The relay F⁷ will actuate and lock by its lower winding to grounded spring on relay E⁷, the calling lamp 705 glowing. Upon the operator noting the glowing of lamp 705 she will manipulate her listening key J⁷. This will close a circuit from talking conductor 523 by way of contacts on keys M⁷, E⁷, J⁷, lower spring on relay D⁷ to the operator's telephone, and through the operator's telephone, upper spring on relay D⁷, spring 706 of key J⁷, contact of key L⁷, contact of key M⁷ to conductor 702. A circuit path can also be traced from spring 706, spring 707, lower spring on relay C⁷, lower winding of relay E⁷, spring 708, contact of key M⁷ to conductor 523. The latter described circuit path will be included in a conductive path with the inside winding of ring-cut-off relay F⁶ in Fig. 5, the latter said relay actuating and locking by its outside winding to off-normal ground, the windings of the back-bridge relay J⁶ will now be energized in series with the last traced path involving spring 707, it being noted that the spring 710 will short circuit the conductor between spring 707 and the winding of relay E⁷, so that if the listening key is restored the lower winding of relay E⁷ will remain energized in series with the windings of the back-bridge relay J⁶. Relay K⁶ will energize in an obvious local circuit of relay J⁶ and relay R⁶ will energize and lock to conductor 501 over an obvious local circuit of relay K⁶, subject to being also energized in a local circuit of relay K⁶ in Fig. 6. When relay E⁷ actuates it unlocks relay F⁷, causing lamp 705 to extinguish, the operator may now converse with the calling party at telephone A. Upon the actuation of relay E⁷ supervisory lamp 713 will glow.
- Extending connection by means of switching plug P⁷*
- If it is now assumed the calling party desires connection with a telephone as T⁸, the operator can complete this connection by inserting plug P⁷ into spring jack j in Fig. 8. The talking conductors of the plug will register with the talking springs of the jack and flex them from the resting contacts, and a circuit can be traced from ground on the ring of the jack, ring of the plug P⁷, conductor 714, lower spring on relay A⁷ to the lamp 715. A circuit can also be traced from ground on conductor 714, spring 717 on relay D⁷ to the winding of relay C⁷, the latter said relay actuating. The operator, while main-

taining the listening key operated, will now manipulate the ringing key K⁷ and apply signaling current from the generator over an obvious path to ring the bell at telephone T⁸. A circuit can now be traced from the telephone T⁸, tip of jack, tip of plug P⁷, spring of key K⁷, spring on relay C⁷, lower winding of relay B⁷ to battery, and from ground upper winding on relay B⁷, spring on relay C⁷, spring of key K⁷, sleeve of plug, sleeve of jack to the telephone T⁸, the relay B⁷ energizing. A circuit can now be traced from ground on conductor 714, spring on relay B⁷, spring of key J⁷, spring of key L⁷, to the winding of relay D⁷, the latter said relay actuating and locking over its spring 717 to grounded conductor 714. The operator's telephone is now disconnected at springs 721 and 722. Regardless of the position of the listening key J⁷, the lower winding of relay E⁷ is now deenergized, a circuit path now being closed from grounded conductor 714, spring on relay A⁷ to the lamp 715. The relay C⁷ will have its energizing path opened at spring 717 and it will deactivate. The deactivation of relay C⁷ will disconnect the windings of relay B⁷ and substitute therefore the windings of the back-bridge relay J⁶ in Fig. 5 wherein the winding of the relay A⁷ is in series with the talking path as may be traced from conductor 702, spring of key M⁷, spring on relay L⁷, winding of relay A⁷, spring on relay C⁷, spring of key K⁷ to the tip of the plug. That is to say that when the relay C⁷ deactivated the condenser 723 is short circuited by the upper spring of relay C⁷, and the companion condenser 724 is shunted by a path including a spring on relay C⁷ and winding of relay A⁷. The lamp 715 is thus extinguished and it will remain so until the party at telephone T⁸ hangs up, whereupon relay A⁷ will deactivate and close an energizing circuit for the lamp 715 from grounded conductor 714, the operator thus being apprised of the condition, and can withdraw the plug P⁷.

Passing call through plug P⁷ by means of switch element Fig. 6

If it is assumed that the calling party has asked for connection to the wrong telephone or, for some other reason it is desired to bring in another telephone or to substitute another telephone as Q⁷ for the telephone T⁸ this will be accomplished in the following manner: The number of telephone Q⁷ will be assumed to be "21". The party at telephone T⁸ will dial the digits 2-1 which will interrupt the circuit including the windings of the back-bridge relay J⁶ correspondingly. Responsive to the two impulses constituting the digit 2 ground on the spring on relay J⁶ will be applied through spring on relay K⁶, conductor 527, spring 528, conductor 529, winding of relay C⁶, winding of the vertical

magnet, side-switch wiper 601 to grounded battery, the wipers 602 to 605 of the switch element Fig. 6 stepping into alignment with the 2 level of bank terminals. At the time 5 that relay C⁶ actuated, its grounded spring energized the relay D⁶ and the inner winding of the private magnet 608, so that when the relay C⁶ deactuates, following the second impulse, the private magnet will deactuate and 10 permit the side-switch wipers 601 and 609 to move into their second positions, so that when the impulse corresponding to the second digit 1 is sent over the traced path to the winding of relay C⁶, the circuit will be completed by 15 way of spring 610 on the busy relay E⁶ to the rotary magnet and side-switch wiper 601 in second position, the rotary magnet operating to step the wipers into bank terminals 611 to 614, the side-switch wipers now stepping 20 into their third positions. The bank terminals accessible from the switch elements in Figs. 5 and 6 have common access to the same lines, and the line groups will correspond. 25 In view of the circuits effecting relays C⁶, D⁶, E⁶, F⁶ and G⁶ corresponding to those on relays C⁵, D⁵, E⁵, F⁵ and G⁵ as regards the testing, hunting, busying, seizing and ringing operations, it is not thought necessary 30 to again detail minutely the corresponding operations with respect to the switch element shown in Fig. 6. Suffice it to say, that when the wipers 602 to 605 are set upon bank terminals 611 to 614, busy ground is applied to conductor 616 and a circuit path can be 35 traced from the signaling circuits in Fig. 6 over conductors 617-618 effective to operating the signal bell at telephone Q⁷, the party at telephone T⁸ hearing the ringing 40 tone with the party at telephone A over an obvious path. When the party at telephone Q⁷ removes his receiver the ring-cut-off relay F⁶ and the back-bridge relay J⁶ and relay K⁶ will actuate over an obvious circuit path, 45 in view of the descriptions of Fig. 5. The calling party at telephone A and the called parties at telephones T⁸ and Q⁷ are now in a Y talking connection. The party at either telephone T⁸ or Q⁷ can now hang up and 50 thereby cause the switch element Figs. 5 or 6, through which connection to his line was attained, to restore its wipers, and this would be accomplished in the following manner: If the party at telephone Q⁷ hangs up first, 55 back-bridge relay J⁶ will deactuate, followed by relay K⁶, whereupon relay L⁶ will be energized. Relay K⁶ will then deactuate, followed by relay L⁶. After relay K⁶ reactuates, 60 and before relay L⁶ deactuates, a circuit can be traced from grounded spring on relay K⁶ winding of relay R⁶, lower spring on relay L⁶, off-normal spring to the release magnet. And if the party at telephone T⁸ hangs up 65 first, the relays J⁶ and K⁶ will deactuate, and relay L⁶ will actuate following the deactua-

tion of relay J⁶, before relay K⁶ has had time to deactuate, relay L⁶ then deactuating. Before relay L⁶ has had time to deactuate, after the deactuation of relay K⁶, a circuit path can be traced from grounded 70 spring on relay K⁶, winding of relay R⁶, spring on relay L⁶, off-normal spring to the release magnet. It is noted in this connection that series relay A⁷ in Fig. 7 deactuated and caused the lamp 715 to be energized over an 75 obvious path as a signal to withdraw the plug P⁷.

Assuming that the party at telephone T⁸ hung up first, thereby restoring the wipers of the switch element Fig. 5, the wipers of 80 the latter said element are in condition for being again operated from normal into connection with an accessible line which may be assumed to be the one leading to telephone R⁷, the number of which is "31", corresponding to bank terminals 530 to 533, and reached over talking conductors 535 and 536.

It being remembered that the switch element shown in Fig. 5 operated to select a line in the 1 level responsive to its leading in trunk being seized, it is noted that due to the actuated and locked condition of relay S⁵ this function is disabled, so that the wipers in the switch element in Fig. 5 is now subject to being operated from normal position only 95 directly. The party at telephone Q⁷ can now send the digits 3-1 and thereby cause the back-bridge relay J⁶ to correspondingly operate to send ground impulses over conductor 527, winding of relay C⁶, to the vertical magnet, the wipers 506 to 509 stepping into alignment with the 3 level, the side-switch wipers moving into their second positions. The impulse corresponding to the second digit 1 will step the wipers into engagement with bank terminals 530 to 533, the side-switch wipers then stepping into their third positions. Signaling current will now be applied to operate the bell at telephone R⁷ in the manner before described when relay 100 E⁶ was operated. Upon the party at telephone R⁷ responding, the ring-cut-off relay F⁶ and the relays J⁶ and K⁶ will be caused to actuate in the manner as before described. A Y talking connection now exists between 115 the calling party at telephone A and the called parties at telephones Q⁷ and R⁷. Either one of the latter two parties may now hang up and restore the wipers of his corresponding switch element Figs. 5 or 6, and 120 the remaining said called party may then operate the restored wipers in connection with a desired accessible line.

It is particularly noted that while the operator's trunk corresponding to plug P⁷ was 125 automatically selected by the wipers of the switch element Fig. 5, responsive to the conductors 3-4 being seized, this automatic functioning is now disabled because of relay S⁵ being actuated and locked. Either switch 130

element may now be directively operated to set its wipers upon the bank terminals corresponding to the line leading to plug P^7 by sending the digits 1—1, corresponding to number "11".

So that if it is assumed that the party at telephone Q^7 sent the digits corresponding to the number "11" in place of number 3—1, the wipers 506 to 509 would be set upon bank terminals 513 to 516, causing the call lamp 705 in Fig. 7 to glow as when the trunk conductors 3—4 were first seized. The operator will answer the call as before described, and by means of plug P^7 may extend the connection to the jack of a desired line.

It will be remembered that when the listening key J^7 was manipulated the lower winding of relay E^7 was placed in series with the windings of the back-bridge relay J^5 , and when the plug P^7 is inserted into the jack of the desired line, the windings of the relay B^7 are connected to the line, due to the actuation of relay C^7 . The lower winding of relay E^7 is still connected in series with the windings of relay J^5 , and the condensers 723—724 are interposed in the connection between the wipers 508—509 and the line called through the plug P^7 . The operator may, or may not, restore the listening key J^7 to prepare a circuit from the winding of relay D^7 to the spring of the relay B^7 before the party at the telephone called responds. However, when he does respond the contacts on relay B^7 will close a circuit path to grounded conductor 714, so when or if the listening key J^7 is restored a circuit path will be closed to energize and lock relay B^7 actuated, to thereby disconnect the winding of relay C^7 , causing it and relay B^7 to deactivate, at the same time short-circuiting the condenser 723 and shunting the condenser 724 by the series winding of relay A^7 so that the back-bridge relay J^5 is now energized in series with the telephone called through the plug P^7 , the receiver thereat being off the switchhook.

The operator by manipulating key L^7 may talk secretly with the party at the telephone called through the plug P^7 . The resistor 725 will be connected through make-before-break spring to maintain the relay J^5 energized as any opening of the energizing circuit of relay J^5 will have the effect of sending an impulse through the relay C^6 and thus move the wipers of the companion switch element to the element Fig. 5.

Operator may pass call by her dial and obtain lamp supervision as to response to passed call

In the event that the operator desires to extend the connection through the agency of the switch element Fig. 6, instead of by means of the plug P^7 , she would manipulate the key M' and thereby introduce the contacts of the dial Z' and the upper winding of relay E' in

bridge of the conductors 523 and 702 over an obvious circuit path involving make-before-break springs on key M' . That is, the contact of the dial Z' and the upper windings of the relay E' will be introduced in series with the windings of back-bridge relay J^5 . The relay E' is thus maintained actuated by its upper winding, its lower winding having been opened by the key M' . The operator may now operate the dial in accordance with the number of any desired line accessible from the switch element Fig. 6, and thereby pass the call in the same manner as the party at telephone Q^7 passed the call in previous descriptions. The operator after restoring the key M' , which served to disconnect the dial and the upper winding of relay E' and substitute the lower winding of relay E' therefor, will now depress the key 727 long enough to permit relays J^5 , K^5 and L^5 to deactivate, to cause the release magnet to operate to restore the wipers 506 to 509, in the manner before described. It is pointed out here that under the condition wherein the switch-arms 540—541—542 in Fig. 5, and 620—621—622 in Fig. 6, are moved to their dotted positions. The use of the key 727 will not be required, since the party responding to a passed call will incidentally cause the restoration of the switch element companion to the switch element connecting to his line. This is accomplished over obvious circuit paths in view of the description of a corresponding operation described with reference to Figs. 5 and 6. Under the latter condition the lamp 713 will glow until the party called in the passing operation responds, at which time the wipers of the switch element Fig. 5 will be restored responsive to the actuation of the back-bridge relay J^6 . This will cause the relay E' to deactivate, whether energized by its upper winding or its lower winding, the lamp 713 extinguishing to indicate the response. The circuit involving conductors 523—702 are now free and subject to being called by either of the switch elements Fig. 5 or Fig. 6, or corresponding elements of other trunks having common access to the lines accessible from the switch elements Figs. 5 and 6.

Restoring switch element if line selected is busy or no answer is obtained

It is pointed out here that in the event that no response is obtained on the line to which the operator passed the connection by means of the switch element Fig. 6 or that this line was encountered busy, the relay G^6 or the relay E^6 , only one of them, will be actuated while the back-bridge relay J^6 will not be energized. Under this condition the operator may desire to pass the call to a substitute telephone, but to do this it will first be necessary to restore the wipers 602 to 605 to normal, and this will be done in the following manner: The operator will manipulate the key 130

10 M^7 to introduce the contacts of the dial Z^7 as described when first passing a call, and thereafter send the digit 1 constituted of one open impulse. This will momentarily retract the armature of relay J^5 and cause the actuation of relay L^5 . Then when the armature of relay J^5 reattracts, while relay L^5 is still actuated, a circuit path can be traced from off-normal ground in Fig. 5, upper spring on relay E^5 , upper attracted spring on relay G^5 , upper attracted spring on relay L^5 , upper spring on relay J^6 , upper inside spring on relay H^6 , conductor 526, off-normal spring in Fig. 6 to the release magnet. The wipers of the switch element Fig. 6 are now ready to be directly operated from normal by the dial Z^7 , to select any desired accessible line.

15 It will be noted that had the operator's position been called by a passing operation through the element Fig. 6, the conductors 523-702 having been selected by the wipers 604-605, the operations described in which relays in Fig. 5 were concerned would, in the last assumed situation, affect corresponding 20 relays and circuits in Fig. 6. For example: sending the digit 1 would cause relay J^6 to momentarily retract its armature, causing relay L^6 to actuate, so that when the armature of relay J^6 reattracts while relay L^6 is still actuated, a circuit can be traced from off-normal ground in Fig. 6, upper spring on relay E^6 , upper attracted spring on relay G^6 , upper attracted spring on relay L^6 , upper spring on relay J^6 , upper inside spring on relay H^6 , conductor 625, lower spring on relay K^6 , off-normal springs in Fig. 5 to the release magnet. The wipers of the switch element in Fig. 6 are now ready to be directly operated from normal by the dial Z^7 , to select any desired accessible line.

25 In the last two descriptions with respect to restoring the switch element Fig. 5 or Fig. 6 from a non-responded-to call, the relays E^5 and E^6 were not actuated while the relays G^5 and G^6 were actuated. It will be noted that had the selected line been encountered busy relays E^5 and E^6 , as the case may be, would have been actuated and the relays G^5 and G^6 , as the case may be, would not have been 30 actuated. In that case the circuit would not include the attracted armature of relay G^5 or G^6 , as the case may be, but would have been direct through the attracted armature of relay E^5 or E^6 , as the case may be.

35 *55 Current over trunk reversed upon response for supervision to main exchange*

40 It is noted that the relay R^5 in Fig. 5 is for the purpose of reversing the relationship of the incoming trunk conductors 3-4 with respect to the windings of relay A^5 . This relay becomes actuated and locked to the conductor 501 responsive to the actuation of either relay K^5 or relay K^6 . That is, whenever a response is first obtained from the operator's

45 trunk circuit in Fig. 7, or from a telephone reached through Figs. 5 or 6, the relay R^5 will be actuated to give supervision or other control back into the main exchange that a 50 response has occurred.

55 *Calling party in main exchange may divert call by annexing number*

60 And in this connection, it will also be noted that had the operator not responded to the call made to her switchboard responsive to the trunk conductors 3-4 being seized simply, or that the calling party in the main exchange desired to himself directly divert the call to a telephone accessible from 65 Figs. 5 and 6, he would thereupon annex the telephone number of such telephone, which may be assumed to be "21", that of telephone 70 Q^7 .

75 The relay A^5 would respond to the two digit series. Responsive to the first two impulses, ground from the spring on relay A^5 will be applied to conductor 527, spring 528, conductor 529, winding of relay C^6 to the vertical magnet in Fig. 6, stepping the wipers 80 602 to 605 into alignment with the 2 level in the same manner and with the same accompanying operations as when telephone Q^7 was described as having been called in a passing operation from telephone T^8 in Fig. 8. 85 When relay A^5 responds to the second digit 1, the rotary magnet will be operated over an obvious circuit path to set the wipers 602 to 605 upon bank terminals 611 to 614, whereupon the relay G^6 will actuate if the line is 90 idle and apply signaling current, or the relay E^6 will actuate if the line is busy. It is to be noted in this connection that the operation of Fig. 6 responsive to relay A^5 is the same as was described when operating it responsive 95 to relay J^5 . In each case the impulses were sent to the conductor 527 and through spring 100 528.

105 If it is now assumed that the party at telephone Q^7 responds, having in mind that the 110 wipers 506 to 509 are still resting upon bank terminals 513 to 516, the latter said wipers will be restored to normal in the following manner: Relays J^5 and K^6 will actuate, 115 whereupon a circuit can be traced from off-normal ground in Fig. 6, upper spring on relay E^6 , attracted upper spring on relay G^6 , upper spring on relay L^6 , upper spring on relay J^6 , upper spring on relay H^6 , conductor 120 625, lower spring on relay K^5 , off-normal spring in Fig. 5 to the release magnet. Had the line corresponding to telephone Q^7 been 125 encountered busy, and therefore the relay E^6 would have actuated and the relay G^6 would not have actuated, the circuit traced from off-normal ground in Fig. 6 would have passed through attracted upper spring on relay G^6 to the upper spring on relay L^6 , avoiding the upper spring on relay G^6 . 130

Party in main exchange can pass call if called line is busy or does not answer

If it is assumed that the party at telephone Q' does not respond or that the line is encountered busy, and the calling party at telephone A in the main exchange desires to pass the call to another telephone as R' accessible from the switch elements Figs. 5 and 6, he will annex the corresponding digits 3-1, whereupon relay A⁵ will respond. The spring 528 is retracted, the relay S⁵ is not actuated and the side-switch wipers 505 and 512 are in their normal positions, and therefore the impulses sent from the grounded spring on relay A⁵ will be sent through the winding of relay C⁵. This will operate the vertical magnet and the private magnet and relay D⁵, responsive to the first digit series and it will operate the rotary magnet and reoperate the private magnet and relay D⁵ responsive to the second digit series of one impulse, thus setting the wipers 506 to 509 on bank terminals 530 to 533, whereupon the relay G⁵ will actuate and apply signaling current if the line is idle, or the relay E⁵ will actuate and apply busy-tone if the line is encountered busy.

It will be noted that when the back-bridge relay J⁵ is being operated in a passing operation, the relay C⁵ will be actuated, and when the back-bridge relay J⁵ is being operated in a passing operation the relay C⁵ will be actuated. Therefore the relay H⁵ will be actuated and locked over an obvious path to off-normal ground in Fig. 5 when a party connected through the switch element Fig. 6 is setting the wipers of the switch element Fig. 5, and the relay H⁵ will be actuated and locked over an obvious path to off-normal ground in Fig. 6 when a party connected through the switch element Fig. 5 is setting the wipers of the switch element Fig. 6. The purpose of the relays H⁵ and H⁶ is to open the circuit towards the main exchange when a back-bridge relay is being operated by dial control, so that the impulses will not be heard by the main exchange party. This arrangement is present in the switch elements Figs. 3 and 4, and was described in more detail in connection with the description of the latter said figures.

Employing the private conductor in the trunk to the operator

Fig. 7A shows an operator's trunk circuit which may be substituted for the trunk circuit shown in Fig. 7, or used auxiliary thereto for a different operator, but employing the private conductor 634. A private conductor was not used in the case of Fig. 7. The Fig. 7A trunk is shown accessible from the switch elements Figs. 5 and 6 at bank position "41". That is, by operating either element Fig. 5 or Fig. 6 in accordance with telephone number "41". The party at telephone Q' when

passing the call to telephone R' as described, could have sent digits 4-1 in place of digits 3-1, and thereupon caused the wipers 602 to 605 to have been set upon bank terminals 629 to 632, whereupon busy-ground will be applied over wiper 603, bank terminal 630, conductor 634 to energize the lamp 729 as a call signal. Upon the operator noting the glowing of the call lamp she will manipulate key V' to connect her telephone to conductors 635-636 and close a circuit involving the windings of the back-bridge relay J⁶, and incidentally energize the relay 730, locking it to the conductor 634, and cause lamp 731 to glow. The operator is now in talking relation with the calling party at the main exchange telephone A. The operator can now pass the call by directly operating the switch element Fig. 5 by operating the dial X', the auxiliary contact set 732 closing at all off-normal positions of the dial to short-circuit the operator's telephone, so that no dial impulses will be heard by the operator. The operator can now restore the wipers of the switch element Fig. 5 by restoring the answering key V'. However, in case the switches 540-541-542 and 620-621-622 in Figs. 5 and 6 are moved to their dotted positions, when a response is obtained the switch element in Fig. 6 will have its wipers automatically restored, which will unlock the relay 730 and extinguish the lamp 731 to indicate the response. The operator of the trunk shown in Fig. 7A may perform the equivalent operations performed by a party at a telephone as R', the key V' corresponding to the switchhook and the dial X' corresponding to the dial at the telephone.

Call from telephone A in Fig. 1 over trunk conductors 5-6 to the switch elements shown in Figs. 12-13

With reference to diagram Fig. 24, it is noted here that the selector switch elements shown in Figs. 12 and 13 do not have direct access to called telephones, obtaining access to called telephones through one of the common connector switches Fig. 19, Fig. 20 and Fig. 21. It will be further noted that in calling a telephone, three digits will be employed, so that 1000 telephones may be reached through the switch elements Figs. 12 and 13, the private automatic exchange constituting what is commonly termed, in general, as a three-pull system as compared with two-pull systems as exemplified by the system employing Figs. 3 and 4, and 5 and 6, before described.

The party at telephone A will initiate a call and operate the calling device in accordance with the numerical position of the trunk line 5-6 leading to Fig. 12. This will complete a connection from telephone A, through switches B and E, to trunk line conductors 5-6 shown in Figs. 1 and 12. A circuit can

now be traced from the upper winding of relay A^{12} , trunk conductor 5, through the telephone A, trunk conductor 6, to the lower winding of relay A^{12} , the latter said relay actuating. Slow releasing release relay E^{12} will energize in a local circuit of relay A^{12} , applying ground to release trunk conductor 201'.

If it is now assumed that the party at telephone A desires to extend a call to telephone A¹⁴, the call will route through the switch element shown in Fig. 12, one of the common switches shown in Figs. 19, 20 and 21 to the said called telephone A¹⁴, the telephone number of which is "211". Upon the party at telephone A sending the first digit 2, relay A^{12} will momentarily retract its armature two times, sending two ground impulses from the spring on relay A^{12} , spring on relay B^{12} , series winding of relay C^{12} , spring on relay D^{12} to the vertical magnet, the vertical magnet operating to step the wipers 202' to 205' into alignment with the 2 level of bank terminals. When the wipers step off-normal, a circuit may be traced from grounded spring on relay B^{12} , attracted spring on relay C^{12} , lower inside spring on relay D^{12} , off-normal contact to the winding of interrupter relay E^{12} , the latter said relay actuating. Whereupon a locking circuit for the latter said relay is closed from ground upper spring on relay E^{12} , contacts on the rotary magnet, off-normal spring, to the winding of relay E^{12} . It is noted that the ground applied to the upper spring on relay E^{12} is also applied to the upper terminal of the winding of relay D^{12} , the latter said relay now having both of its winding terminals applied to ground. Relay C^{12} will deactivate following the last impulse, whereupon ground on spring on relay B^{12} will be applied through spring on relay C^{12} , attracted spring on relay E^{12} to the rotary magnet, the rotary magnet operating to step the wipers 202' to 205' to the first set of bank terminals 206' to 209' of the 2 level.

The first set of bank terminals of the 2 level extends to the switch shown in Fig. 19. The second set of bank terminals of the 2 level extends to the switch shown in Fig. 20. The third set of bank terminals of the 2 level extends to the switch shown in Fig. 21. Ordinarily there would be ten sets of bank terminals per level, although there might be more or less. The sets of bank terminals accessible from the switch in Fig. 12 are tied by means of the vertical conductors on the right of Figs. 12 and 13 to correspondingly position bank terminals accessible from Fig. 13, and moreover, are common to corresponding bank terminals accessible from other pairs of trunk switch elements corresponding to Figs. 12 and 13. That is, the switch elements Figs. 12 and 13 comprise an interlinked pair of selector switch elements forming what may be conveniently termed a duplex selector

switch. There will be a duplex selector switch terminating each trunk at the private automatic exchange, one trunk only being illustrated. Thus, the switches shown in Figs. 19, 20 and 21 may be commonly seized from the first, second and third sets of bank terminals of the 2 level of each of the switch elements terminating the various trunks. Therefore, there will be as many switches such as shown in Figs. 19, 20 and 21 for the 2 level. There will therefore be a group of switches like shown in Figs. 19, 20 and 21 for each of the levels accessible in common from switch elements as shown in Figs. 12 and 13. Each of the groups of switch elements Figs. 19, 20 and 21 will have access to one hundred local lines. Thus each level accessible from the switch elements Figs. 12 and 13 will refer to one hundred local lines. So that when the switch element Fig. 12 selected the 2 level it is determined that the line called belongs to the 2 hundred group. One of the switch elements Figs. 19, 20 or 21 thus determined will be operated to select the particular line of the 2 hundred group determined.

Going back to the condition ensuing when the wipers 202' to 205' were set upon bank terminals 206' to 209', it will be assumed that the switch shown in Fig. 19 was in use having been previously seized by some other accessible switch, not shown, and therefore the conductor 210' will constitute busy-ground to guard the previously established connection to switch Fig. 19 against intrusion. So that when wiper 202' encountered ground on bank terminal 206', this ground will be communicated through upper spring on relay D^{12} , contacts on the rotary magnet, off-normal springs to the winding of relay E^{12} , the latter said relay actuating and locking over the circuit before traced, and the rotary magnet being again energized to step the wipers to the second set of bank terminals, and if wiper 202' now finds ground on bank terminal 213' corresponding to the switch Fig. 20, the last operation will be repeated to step the wipers a further step so that wiper 202' will rest upon bank terminal 214', corresponding to the switch Fig. 21. If it is assumed that the switch Fig. 21 is idle and therefore bank terminal 24' will not constitute ground potential, there will be no ground applied to the upper terminal of the winding of relay D^{12} when relay E^{12} deactuates, so that a circuit path can now be traced from battery, winding of relay E^{12} , off-normal springs, contact on the rotary magnet, winding of relay D^{12} , to grounded conductor 201'. The relay D^{12} will operatively energize in this circuit including the winding of relay E^{12} , while the relay E^{12} will not, due to its marginal adjustment. It is noted that relays A^{12} and B^{12} remain energized and that the relay G^{12} has not yet actuated. However, a circuit path can now

be traced from grounded conductor 201' through attracted upper spring of relay D¹², wiper 202', bank terminal 214', conductor 216' to the winding of relay D²¹ in Fig. 21, the latter said relay actuating. Relay B²¹ will energize in a local circuit of relay D²¹ to prepare a circuit for the release magnet in Fig. 21. It is noted that the connector switch Fig. 21 is now busy-guarded against all accessible switch elements due to the ground on conductor 216'.

At the time relay D²¹ energized the relay E²¹ was also energized over conductor 216'. A circuit can now be traced from battery on spring 220', winding of the vertical magnet in Fig. 21, winding of series relay C²¹, spring on relay F²¹, conductor 221', bank terminal 222', wiper 203', spring on relay P¹², winding of relay G¹² to opposing battery, neither 15 relays F²¹ or G¹² in the last described circuit energizing. The circuit traced to the winding of relay G¹² may be further traced from wiper 203' through the winding the spring on relay P¹², retracted lower spring on relay 20 G¹², to the upper terminal of the winding of relay C¹², through lower spring on relay C¹², conductor 243', to the vertical magnet in Fig. 6 to opposing battery.

When party at telephone A now annexes 30 the second digit 1, relay A¹² in Fig. 12 will momentarily retract its grounded spring to send a ground impulse through the windings of relays C¹² and P¹² and wiper 203', effective to operate the said relays, sustaining 35 them consistent with their slow releasing characteristics, and also causing this ground impulse to be sent through the relay C²¹ and the vertical magnet in Fig. 21, stepping the wipers 225' to 227' into alignment with the 40 1 level of bank terminals. The vertical off-normal springs in Fig. 21 will now be open. When relay C²¹ actuated responsive to the impulse, ground from its spring locked the relay E²¹ to insure that it will sustain after 45 the vertical off-normal springs have operated, and this ground is also applied to energize the relay G²¹, and lock it for the period that relay C²¹ sustains its spring attracted. Following the impulse to the vertical magnet 50 of Fig. 21, which caused the wipers to be aligned with the 1 bank level, the relay C²¹ will deactivate followed by the deactivations of relays G²¹ and E²¹. Upon the party at 55 telephone A now sending the third digit 1, the same operations as last described will take place in the switch element Fig. 12, and the ground impulse will be sent through the winding of relay C²¹ as before, and through the rotary magnet, retracted upper spring of 60 relay E²¹ to grounded battery, the rotary magnet operating to set the wipers 225' to 227' on bank terminals 228' to 230', corresponding to the line leading to telephone A¹⁴ in Fig. 14.

At the time that the wipers 225' to

227' were stepped in to bank terminals 228' to 230', the rotary off-normal springs were closed, so that when relay C²¹ retracted its grounded spring this ground energized the relay F²¹, which applied ground through the upper spring of relay F²¹ over conductor 221', bank terminal 222', wiper 203', spring on relay P¹² to the winding of relay G¹², the latter said relay actuating.

Encountering called line busy causes busy-tone to be applied audible to calling party

If bank terminal 228' constitutes ground potential when wiper 225' is set upon it, and that relay G²¹ is maintained actuated, locked to this ground, tone from source T²¹ will be applied through the middle spring on relay G²¹, talking conductor 231', bank terminal 232', wiper 204', upper inside spring on relay G¹², spring on ring cut-off relay F¹², outside winding of the latter said relay to grounded battery. This tone will be inductively applied to the inside winding of the latter said relay, lower winding of back-bridge relay J¹² and over an obvious path through the calling telephone A to the upper winding of relay A¹², thus apprising the calling party of the busy condition encountered.

Encountering called line idle

However, if it is assumed that the bank terminal 228' does not constitute ground potential when the wiper 225' is set upon it, the relay G²¹ will not be maintained actuated after relay C²¹ deactuates, so that ground will be applied through the upper springs of relay G²¹ to thereupon busy-ground the bank terminal 228' and its attachments, to guard the line leading to telephone A¹⁴ against intrusion, and to operate the cut-off relay of the line switch.

A circuit path can now be traced from ring ing current generator, spring on interrupter relay, lower spring on relay F¹², spring on relay G¹², wiper 205', bank terminal 234', conductor 235', lower spring on relay G²¹, wiper 227', bank terminal 230', conductor 236', bell of telephone A¹⁴, conductor 237', bank terminal 229', wiper 226', spring on relay G²¹, conductor 231', bank terminal 232', wiper 204', spring on relay G¹², spring on and outside winding of relay F¹² to grounded battery. The relay F¹² will not actuate over this inductive path involving the condenser in the bell at telephone A¹⁴, but ringing induction will be perceived by the party at telephone A over the path traced for the busy-tone from the windings of relay F¹².

Called party responds

Upon the party at telephone A¹⁴ removing his receiver, the relay F¹² will be operatively energized to cut off the signaling current and lock its inside winding to off-normal ground, and apply the latter ground through

the lower winding of back-bridge relay J^{12} to the lower talking conductor, so that a circuit can now be traced over an obvious path including the windings of relay J^{12} and the called telephone A^{14} , the relay J^{12} actuating. Ground from spring on relay J^{12} will be applied over conductor 238', lower spring of relay M^{12} in Fig. 13, conductor 239', to the winding of relay K^{12} in Fig. 12, the latter said relay actuating. Relay M^{12} will energize in a local circuit of relay K^{12} . The calling party at telephone A is now in talking relation with the called party at telephone A^{14} .

It is to be particularly noted with respect to the foregoing descriptions that the switch Fig. 21 is maintained in seizure of the called line by ground sent ahead from conductor 201' in Fig. 12. Also that the relay G^{12} does not operate to connect through the talking conductors until the wipers of the switch Fig. 21 are operated in vertical and rotary movements.

The switch-arm 240' may be closed, if desired, and under this condition when a busy condition is encountered by the wiper 235' and the relay C^{21} deactuates, ground applied through the switch-arm 240', spring 241', lower spring on relay E^{21} will maintain ground to the wiper 225', so that the bank terminal 228' will be maintained grounded until the wipers of switch Fig. 21 are restored, regardless of the fact that the line called may in the mean time become idle. With the switch-arm 240' in its open position, if the busy-ground is removed from terminal 228', the relay G^{21} will deactuate and forthwith apply ground to said terminal 228', and also close the conductors 231' and 235' to the conductors 237' and 236', respectively. Whereupon the bell at telephone A^{14} will be operated. That is closing switch 240' will cause the switch Fig. 21 to lock against thereafter effecting a talking connection to the line encountered busy, for the duration party at telephone A keeps his receiver off the switchhook.

Party at telephone A^{14} hangs up first

If it is now assumed that the party at telephone A^{14} hangs up, relay J^{12} will deactuate followed by relays K^{12} and M^{12} , wherein relay L^{12} will actuate before relay M^{12} has had time to deactuate and will thereafter deactuate consistent with its release characteristic. When relay M^{12} deactuates, and before relay L^{12} has had time to deactuate, a circuit path can be traced from grounded spring on relay M^{12} , winding of relay N^{12} , lower spring of relay L^{12} , off-normal spring, spring on relay M^{12} to the release magnet, the wipers 202' to 205' being thereby restored to normal. Ground will thus be removed from conductor 216', causing relays D^{21} and B^{21} to deactuate in sequence, wherein before relay B^{21} deactuates, a circuit path can be traced from

grounded spring on relay D^{21} , spring on relay B^{21} to the release magnet, the wipers 225' to 227' being thereby restored to normal.

In this connection it will be noted that incidental to the wipers of switch element Fig. 70 12 being restored, ground from spring on relay J^{12} is applied through spring on relay M^{12} , conductor 242', lower spring on relay C^{12} , conductor 243', winding of slow releasing series relay C^{13} , lower spring of relay D^{13} to the vertical magnet, the wipers 245' to 248' being thus stepped into alignment with the 1 bank level, and they will be immediately restored to normal position by the operation of the release magnet which is energized over a circuit traced from the release magnet, spring on relay M^{13} , off-normal springs, conductor 250', attracted spring on relay N^{12} , conductor 251', upper spring on relay G^{12} , to off-normal ground.

It is noted, in view of descriptions to follow, that whenever ground is removed from conductor 216' by reason of the antecedent switch restoring its wipers, that the wipers of switch Fig. 21 will be caused to restore to normal. And it will also be noted in this connection that this applies to Figs. 19 and 20, the circuits of which are like those disclosed in Fig. 21 and may be employed interchangeably depending upon traffic conditions, wherein Fig. 19 would be used normally as first choice, Fig. 20 as second choice, and Fig. 21 as third choice. In view of what has been detailed in connection with Fig. 21, the operation of the switches Figs. 19 and 20 will be understood in descriptions about to be made, without detailing these operations of Figs. 20 and 21.

Party at telephone A^{22} passes call by means of switch element Fig. 13 and connector Fig. 19

Going back to the condition at the time the party at telephone A^{14} responded, it may be assumed that the party at telephone A^{14} wishes to transfer the connection to the telephone C^{14} in Fig. 14, the telephone number of which is "231". Accordingly, he will operate his dial in accordance with digits 2-3-1. Responsive to the first digit 2, the relay J^{12} will momentarily retract its armature two times, the relay L^{12} actuating and sustaining until after the termination of the series. A ground impulse will be sent from the lower spring on relay J^{12} , lower inside spring on relay M^{12} , lower spring on relay C^{12} , conductor 243' winding of relay C^{13} in Fig. 13, lower spring of relay D^{13} to the vertical magnet. This will step the wipers 245' to 248' into alignment with the 2 level.

At the time relay C^{13} actuated it applied ground received from conductor 201' over conductor 252', spring on relay C^{13} , conductor 253', to the winding of relay H^{12} in Fig. 12, locking the latter said relay over conduc-

tor 254', upper spring on relay G¹³ in Fig. 13 to off-normal ground, so that the relay H¹² will remain locked until relay G¹³ actuates or the wipers 245' to 248' are restored to normal. Ground from conductor 201' will also be applied to the spring of relay C¹³, off-normal springs, to the winding of interrupter relay E¹³, the latter said relay actuating and establishing a locking circuit for itself from ground upper spring of relay E¹³, contacts on the rotary magnet, off-normal springs, to the winding of relay E¹³.

When relay C¹³ retracts its armature following the last impulse of the series, ground received over conductor 252' is applied through the spring on relay C¹³, lower spring on relay E¹³, to the winding of the rotary magnet, causing it to operate and drive the wipers 245' to 248' in to the first set of bank terminals 255' to 258', corresponding to the switch Fig. 19 which is now assumed to be idle, and therefore ground potential will not exist on bank terminal 255'. Under this condition, when the relay E¹³ retracts its upper spring and removes the locking ground from the latter said relay, this ground will also be removed from the upper terminal of the winding of relay D¹³ so that the windings of relays E¹³ and D¹³ are now in series with battery derived through the winding of relay E¹³ to ground on the conductor 201'. Relay D¹³ will actuate under the condition while relay E¹³, due to its marginal adjustment, will remain unactuated. Ground will now be applied from conductor 252', upper spring on relay D¹³, wiper 245', to bank terminal 255', to place busy-ground on conductor 210', to guard the switch Fig. 19 against being seized from other accessible switch elements corresponding to Figs. 12 and 13 having common access to the switch Fig. 19.

Had the bank terminal 255' constituted busy-ground when wiper 245' engaged it, this ground would have maintained ground potential on the upper terminal of the winding of relay D¹³, and would have reenergized and locked the relay E¹³, so that the rotary magnet would be energized over the before described path to drive the wipers to the next set of bank terminals, testing same in the manner that the first set was tested.

Going back to the condition wherein the switch Fig. 19 was seized, ground on conductor 210' causes relays D¹³, B¹³ and E¹³ to actuate. Upon the party at telephone A¹⁴ operating his dial in accordance with the second digit 3, relay J¹² will correspondingly operate to send ground impulses over the circuit before described, through the winding of relay C¹³, now continuing to attracted spring on relay D¹³, spring on relay G¹³, winding of relay P¹³, wiper 246', bank terminal 256', conductor 264', spring on relay F¹³ in Fig. 19, winding of relay C¹³, vertical magnet, attracted upper spring on relay E¹³ to

grounded battery. The wipers 261' to 263' being thereby stepped into alignment with the 3 level of bank terminals. Relay C¹³ will now deactivate and unlock the relay E¹³, and relay G¹³, which actuated idly when relay C¹³ actuated, will deactivate.

When the party at telephone A¹⁴ now operates the dial in accordance with the third digit 1 an impulse will be sent from the grounded spring on relay J¹² as before, through the relay C¹⁰, this time through the winding of the rotary magnet, retracted armature of relay E¹⁰ to grounded battery, the wipers 261' to 263' being set upon bank terminals 265' to 267', corresponding to telephone C¹⁴. Assuming that the line leading to telephone C¹⁴ is idle, conductor 268' to which the bank terminal 265' is attached, will not constitute busy-ground, and therefore the relay G¹⁰ will not be locked and will deactivate following the deactivation of relay C¹⁰, and by its upper spring apply busy-ground to bank terminal 265' to guard the line against intrusion and operate the line cut-off relay of the line switch not shown.

Response to passed call causes the extension to the passing party's telephone to be broken down

At the time that relay C¹⁰ retracts its spring, relay F¹⁰ actuates and applies ground through its spring over conductor 264', bank terminal 256', wiper 246', spring on relay P¹³, to the winding of relay G¹³, the latter said relay actuating. A circuit can now be traced from the ringing current generator, spring on interrupter relay, lower spring on ring cut-off relay F¹³, attracted spring on relay G¹³, wiper 248', bank terminal 258', conductor 270', lower spring on relay G¹⁰ in Fig. 19, wiper 263', bank terminal 267', conductor 271', bell of telephone C¹⁴, conductor 272', bank terminal 266', wiper 262', middle spring on relay G¹⁰, conductor 273', bank terminal 257', wiper 247', spring on relay G¹³, upper spring and outside winding of relay F¹³, to grounded battery. Relay F¹³ will not operatively energize over the inductive circuit including the condenser in telephone C¹⁴, but when the party at the telephone removes the receiver the relay F¹³ will operatively energize and lock by its inside winding to off-normal ground, the latter said ground being also applied through the lower winding of back-bridge relay J¹³, to the lower talking conductor, relay J¹³ will thus energize in series with telephone C¹⁴. Ground from the lower spring on relay J¹³ will be applied over conductor 274', attracted lower middle spring on relay M¹² to the release magnet in Fig. 12, the wipers 202' to 205' being now restored to normal position, and the switch Fig. 21 will also have its wipers restored, disconnecting the telephone A¹⁴ from the connection.

Relay J¹² will now deactivate, so that when

relay M^{12} deactuates a circuit path may be traced from grounded spring on relay J^{13} , conductor 274', conductor 275', winding of relay K^{13} , the latter said relay actuating, relay M^{13} thereupon actuating in a local circuit of relay K^{13} . The calling party at telephone A is now in talking relation with the party at telephone C^{14} .

The party at telephone C^{14} may now hang up, causing relay J^{13} to deactuate, followed by relays K^{13} and M^{13} , wherein relay L^{13} will actuate and sustain until after relay M^{13} deactuates, so that a circuit can be traced from grounded spring on relay M^{13} to the winding of relay N^{13} , lower spring on relay L^{13} , off-normal springs, spring of relay M^{13} to the release magnet, restoring the wipers 245' to 248'. At the time that relay J^{13} deactuates, its lower spring applied ground over conductor 242', winding of relay C^{12} in Fig. 12, lower spring of relay D^{12} to the vertical magnet, thus stepping the wipers 202' to 205' into alignment with the 1 bank level. However, these wipers are immediately restored due to off-normal ground being applied through upper spring on relay G^{13} , spring on relay N^{13} , conductor 276', off-normal springs in Fig. 12, middle lower spring on relay M^{12} to the release magnet.

³⁰ *Party at telephone C^{14} passes call to telephone D^{14}*

The party at telephone C^{14} may now operate his dial in accordance with telephone number "221" and thereby pass the call to telephone D^{14} in Fig. 14.

Before describing the passing of the call to telephone D^{14} , it is pointed out that when the party at telephone A directly called telephone A^{14} he caused the relay A^{12} to operate in accordance with the successive digits 2-1-1, which sent grounded impulses to the lower terminal of the winding of relay C^{12} , and through said winding and lower spring of relay D^{12} to the vertical magnet, and that after the relay D^{12} actuates when a trunk has been found, these impulses are diverted from the vertical magnet to the wiper 203' and to the impulse conductor of the succeeding switch. It is further pointed out that when the party at telephone C^{14} operates his dial to pass the call through the agency of the switch element Fig. 12, wherein the relay J^{13} will operate responsive to the dial impulses that ground impulses will be sent from the lower spring on relay J^{13} , spring on relay M^{13} , conductor 242', to the lower terminal of the winding of relay C^{12} , and through said winding and lower spring on relay D^{12} to the vertical magnet, so that after the relay D^{12} actuates when a trunk has been found these impulses are diverted from the vertical magnet to the wiper 203' and to the impulse conductor of the succeeding switch.

Call may be passed from main exchange telephone A or local telephone C^{14}

It is thus seen that so far as operating the switch element Fig. 12 is concerned, and the succeeding connector switch, it is immaterial whether relay A^{12} directs this operation or whether it is directed by relay J^{13} . So that, the party at telephone C^{14} or the party at telephone A may send impulses corresponding to telephone "211" and extend the connection through the switch element Fig. 12 through one of the connector switches Fig. 19, Fig. 20 or Fig. 21 to telephone D^{14} , remembering that the switch Fig. 19 is busy in the connection from switch element Fig. 13 to telephone C^{14} , and therefore the bank terminal 206' will constitute busy-ground. So that the wipers of element Fig. 12 will rotate off and select the next set of bank terminals 213', 277', 278' and 279'. Assuming that bank terminal 213' is not grounded, the relay D^{12} will actuate in the manner before described, whereupon relays D^{20} , B^{20} and E^{20} in Fig. 20 will actuate. The last two digits 1-1 will set the wipers 280' to 282' upon bank terminals 283' to 285', leading over conductors 286', 287', 288' to the winding of the cut-off relay of the line switch, not shown, and the talking terminals of the telephone D^{14} respectively.

When the party at telephone D^{14} responds to the signaling current applied from the ringing generator in Fig. 12, in the manner before described, with respect to the call to telephone A^{14} , the relay J^{12} will energize and will apply ground from its lower spring over conductor 238', attracted spring on relay M^{13} to the release magnet of the element Fig. 13, restoring its wipers. Whereupon the connector switch Fig. 19 will also restore.

The party at telephone A, or the party at telephone D^{14} , can now call telephone E^{14} , having telephone number "241", by reoperating the switch element Fig. 13 to select switch Fig. 19 and operate the latter said switch so that its wipers are set upon bank terminals 289' to 291' to complete the connection to the telephone E^{14} . Then when the party at telephone E^{14} responds, the switch element Fig. 12 will thereby have its wipers restored, and the switch Fig. 20 will have its wipers restored from the line leading to telephone D^{14} , subject to being reoperated from the telephone A or the telephone E^{14} .

When a connector seizes it applies control to energize a relay in the antecedent switch

From the foregoing descriptions it will be noted that when one of the switches Figs. 19 to 21 is set upon a set of bank terminals, ground will be applied back from the concerned one of the latter said switches to the antecedent switch element as Fig. 12 or Fig. 13 over the impulse conductor as 221', to cause the relay as G^{12} or G^{13} , as the case may

be, to actuate, and that this condition will ensue regardless of whether the telephone line selected is busy or idle. So that in the event that no response is obtained from a local telephone as A¹⁴, C¹⁴, D¹⁴, or E¹⁴, or that the busy-tone is heard indicating that connection to the selected line is barred, the party passing the call, or the calling party at telephone A may thereafter dial digits corresponding to a substitute line leading to a local telephone, and effect connection thereto by a new operation wherein the switch element as Fig. 12 or Fig. 13 will be re-employed, together with the first idle one of the connector switches Figs. 19 to 21 encountered.

In connection with the last foregoing, it will first be necessary to restore the switches operated in the futile passed call, wherein no response was obtained or the telephone line was busy, and this will be done in the following manner: Assume that at the time connection was effected through the switch element Fig. 12, and the switch Fig. 21 to telephone A¹⁴, wherein the party at telephone A¹⁴ passed the call by means of switch element Fig. 13 and switch Fig. 19 to telephone C¹⁴, the line to the latter said telephone was encountered busy, or that no response was obtained, and the party at telephone A¹⁴ then elected to pass the call to telephone D¹⁴, he would send the digit 1 which would cause relay J¹² to momentarily retract its armature, causing relay L¹² to actuate and sustain actuated consistent with its characteristic. A circuit path can now be traced from off-normal ground in Fig. 12, attracted spring on relay G¹², attracted spring on relay L¹², attracted spring on relay J¹², upper spring on relay H¹², conductor 250', off-normal springs in Fig. 13, spring of relay M¹³, to the release magnet in Fig. 13 restoring the wipers 245' to 248', and also the wipers of the switch Fig. 19. The party at telephone A¹⁴ can now reoperate the switch element Fig. 13 and the switch Fig. 19 (or Fig. 20 or 21) to pass the call to another telephone as telephone E¹⁴, for example, in the same manner as passing the call to the line corresponding to telephone C¹⁴.

Switches operated in passing a call may be restored by sending digit 1

In view of the last foregoing, it will be noted that if a call were being passed by means of the switch element Fig. 12 from a local telephone connected through the switch element Fig. 13, and an unresponded or busy condition is encountered, sending digit 1 to correspondingly operate relay J¹³ will cause a circuit to be completed from off-normal ground in Fig. 13, attracted spring on relay G¹³, spring on relay L¹³, spring on relay J¹³, spring on relay H¹³, conductor 276', off-normal springs in Fig. 13, spring on relay M¹²

to the release magnet, restoring the wipers 202' to 205'.

The foregoing sending of digit 1 to restore the switch element companion to the one connected to the telephone directing the passing operation does not apply in passing operations or in making successive calls while holding the trunk line 5-6, from telephone A. However, assuming that when the call was extended directly by the party at telephone A to the telephone A¹⁴ no response was obtained, or a busy condition was encountered, the party at telephone A could forthwith annex the telephone number of another telephone as C¹⁴ and operate the switch element Fig. 13, and switch element Fig. 19 into connection with the line corresponding to telephone C¹⁴, responsive to relay A¹², in the manner before set out. At the time that the wipers of switch Fig. 19 are set upon the selected line, ground will be applied over conductor 264' to cause the actuation of relay G¹³, whereupon a circuit can be traced from off-normal ground in Fig. 13, attracted spring on relay G¹³, retracted springs on relays L¹³, M¹³, and H¹³, conductor 276', off-normal springs in switch element Fig. 12, spring on relay M¹² to release magnet, the wipers 202' to 205' restoring. If it is further assumed that the line corresponding to C¹⁴ is encountered busy or the party thereon does not respond, the party at telephone A may annex the number of a desired local telephone and complete the call through the switch element Fig. 12 and an idle one of the switches Fig. 19 to Fig. 21, and when the relay G¹² actuates responsive to the selection of the line, a circuit can be traced from off-normal ground in Fig. 12, attracted spring on relay G¹², retracted springs on relays L¹², M¹² and H¹², conductor 250', off-normal springs in Fig. 13, spring on relay M¹³ to the release magnet, the wipers 245' to 248' restoring.

Call may be passed from main exchange

It will be noted in this connection that if after the telephone A directly called the telephone A¹⁴ and obtained a response, that the party at telephone A then desired to himself directly pass the call, he would annex digits corresponding to the number of the desired telephone, operating the switch element Fig. 13 through the agency of the relay A¹², this time, however, due to the party at A¹⁴ having his receiver off the switch-hook, relays J¹², K¹² and M¹² will be operated and therefore the circuit for operating the release magnet in Fig. 12 will not be closed simply responsive to the connection being completed through the switch element Fig. 13 and one of the common switches Figs. 19 to 21 being set upon the terminals of the desired telephone line and thereupon cause relay G¹³

to actuate and relay H^{12} to unlock. However, upon a response being obtained on the last called line, linked through switch element Fig. 13, wherein relay J^{12} will actuate, ground can be traced from spring on relay J^{13} , conductor 274', lower middle spring on relay M^{12} to the release magnet, the wipers 202' to 205' restoring. And it will be noted that should a responded connection ensue through the switch element Fig. 13, and the call then be passed, directed from the telephone A, employing the switch element Fig. 12, while the party at the telephone reached through the switch element Fig. 13 retains his receiver off the switchhook, when the last called party responds and causes relay J^{12} to actuate, ground from the lower spring on this relay will be applied over conductor 238', attracted middle lower spring on relay M^{13} to the release magnet in Fig. 13, the wipers 245' to 248' restoring.

Main exchange party abandons call

If the party at telephone A abandons the call, under the condition that one of the switch elements Figs. 12 or 13 is in a connection to a telephone line in a responded state, the relays A^{12} and B^{12} will deactivate in sequence, removing ground from conductors 201' and 252', so that the relay D^{12} or D^{13} , as the case may be, will deactivate and remove ground from the conductor corresponding to 216' in Fig. 21, so that the concerned switch Fig. 19 to Fig. 21 in the connection will restore its wipers and the relay corresponding to F^{21} will remove ground energizing the relay G^{12} or G^{13} , as the case may be, which will in turn cause relays J^{12} — K^{12} — M^{12} , or relays J^{13} — K^{13} — M^{13} , as the case may be, to deactivate, so that an obvious circuit path will be closed from ground on spring on relay B^{12} to the release magnet in Fig. 12 or Fig. 13, as the case may be.

Call from telephone A in Fig. 1 over trunk conductors 7—8 to the switch elements shown in Figs. 16—17

With reference to diagram Fig. 25, the party at telephone A will initiate a call and operate the calling device in accordance with the numerical position of the trunk line leading to the duplex connector Figs. 16—17. This will complete a connection from telephone A through switches B and F to trunk line conductors 7—8 shown in Figs. 1 and 16. A circuit can now be traced from battery, upper winding of line relay A^{16} , conductor 7, telephone A, conductor 8, lower winding of relay A^{16} to ground, the relays A^{16} and B^{16} actuating. Ground from the upper spring on relay B^{16} is applied to release trunk conductor 601'.

Before going into the detailed operation of the interlinked pair of connector switch elements in Figs. 16 and 17, it is pointed out

that these are group selecting, wherein circuits corresponding to those described in connection with Figs. 3 and 4, and 5 and 6, respectively, are present, and their group selecting operation will therefore be understood. The relays L^{16} and L^{17} correspond to relays L^3 and L^4 in Figs. 3 and 4, and relays H^5 and H^6 in Figs. 5 and 6, respectively. That is, the relay L^{16} will be energized and locked to off-normal ground in Fig. 17 whenever relay C^{17} actuates, and relay L^{17} will be energized and locked to off-normal ground in Fig. 16 whenever relay C^{16} actuates. Relay R^{16} will be energized and locked to conductor 601' whenever either relay K^{16} or K^{17} actuates, and it will be noted that whenever either of the relays J^{16} or J^{17} are in their actuated state, relay Q^{16} will be energized to change the character of signaling current supply to the switch elements Figs. 16—17 from normally 33-cycle to 50-cycle. The busy relays E^{16} and E^{17} operate like relays E^3 and E^4 in Figs. 3—4, and E^5 and E^6 in Figs. 5—6, respectively. The switch-arms 603' to 607' and 700' correspond to switch-arms 367, 366, 436, 437, 365 and 435 in Figs. 3 and 4, respectively.

So that it is believed, in view of previous descriptions, with respect to Figs. 3 to 6, it will not be necessary in imparting a comprehensive disclosure to detail operations in Figs. 16—17 that are obvious in view of the latter said previous descriptions.

Extending call from telephone A to telephone Q¹⁰

If it is assumed that the party at telephone A desires to extend the connection to telephone Q^{10} in Fig. 10, the telephone number of which is "11", he will operate his dial in accordance with the digits 1—1 and cause wipers 610' to 613' to be set upon the first set of bank terminals of the 1 level, thereby completing a connection to the line corresponding to telephone Q^{10} . 33-cycle signaling current will now be applied from source G^{16} to operate the bell of telephone Q^{10} . When the party at telephone Q^{10} responds, a circuit path over conductors 614'—615' will be included in the energizing path of back-bridge relay K^{16} , ring cut-off relay F^{16} having just previously actuated due to the response. Relay J^{16} energized in a local circuit of relay K^{16} , and relay R^{16} energizes in a local circuit of relay K^{16} and then locks to conductor 601'. As long as relay J^{16} (and also relay J^{17} , as will appear) is actuated, relay Q^{16} will be maintained actuated, to change the signaling current applied to the switch elements Figs. 16—17 to 50-cycle, for an object which will appear presently, having in mind that the telephone bells will respond to either 33 or 50-cycles, 50-cycle current causing the bells to ring more rapidly than when operated by 33-cy-

cle current, and this is discernable to those who may hear the ringing.

The party at telephone Q^{10} is now in talking relation with the party at telephone A over an obvious circuit path. The party at telephone Q^{10} may now pass the call to another telephone as R^{10} , the telephone number of which is "21", by sending digits 2-1, and correspondingly operating relay K^{16} to send corresponding ground impulses over conductor 618', through the winding of relay C^{17} to operate the vertical and rotary magnets in switch element Fig. 17 to set the wipers 701' to 704' upon the first set of bank terminals of the 2 level, and thereupon apply 50-cycle signaling current from source M^{16} to operate the bell at telephone R^{10} . When the party at telephone R^{10} responds, a circuit path over conductors 705'-706' will be included in the energizing path of back-bridge relay K^{17} , ring cut-off relay F^{17} having just previously actuated due to the response. Relay J^{17} energizes in a local circuit of relay K^{17} , and applies ground over conductor 708' to maintain the relay Q^{16} energized, should the relay J^{16} deactivate. The relay J^{16} will deactivate if the party at telephone Q^{10} hangs up, or in the event that switch-arms 603' to 607' and 700' have been moved to their dotted positions, at the time the party at R^{10} responded and thereby caused the restoration of the switch element Fig. 16.

Party at telephone Q^{10} responds and then hangs up

If it is assumed that after the party at telephone R^{10} responded and a Y talking connection then existed between the telephone A and the telephones Q^{10} and R^{10} , the party at telephone Q^{10} hung up, the wipers 610' to 613' of the switch element Fig. 16 will restore, and may be again operated from the dial at telephone R^{10} . The party at telephone R^{10} could have alternatively hung up to restore wipers 701' to 704' and the party at telephone Q^{10} could then have in the same manner operated his dial to set the latter said wipers on the terminals of a desired line.

Party at telephone A may pass call

It will be noted that after the party at telephone Q^{10} responded, the call could have been passed by the switch element Fig. 17 responsive to the dial at telephone A in place of the dial at telephone Q^{10} being similarly operated. In the latter case in place of the switch element Fig. 17 being directed by back-bridge relay K^{16} , it would be directed by the line relay A^{16} , sending the ground impulses over conductor 618' in both cases. The relay Q^{16} will be in its operated state under this condition and the bell at the telephone called would be operated by 50-cycle

signaling current to indicate that there was a local telephone Q^{16} in a Y branch of the connection to his line.

Party at telephone Q^{10} may pass call to telephone T^{10}

If it is assumed that the party at telephone Q^{10} had operated his dial in accordance with digits 3-1 in place of digits 2-1, when passing the call, the wipers 701' to 704' would have been set upon the first set of bank terminals of the 3 level, so that signaling current of 50-cycles would be applied over conductors 715'-716' operatively effective to the tuned bell at telephone T^{10} , and upon the party at the latter said telephone responding a Y talking connection would exist between telephones A, Q^{10} and T^{10} .

Party at telephone A may have called telephone T^{10} in place of telephone Q^{10}

If it is now assumed that in place of the party at telephone A calling the telephone Q^{10} , he had called the line leading to telephone T^{10} by sending digits 3-1. Under this latter assumed condition 33-cycle signaling current would be applied operatively effective to the tuned relay A^{10} , not operatively effective to the bell at telephone T^{10} .

It is thus clear that when a call is made to the line leading to telephone T^{10} wherein there is no local telephone in a Y connection, wherein the relay Q^{16} would not be actuated in a local circuit of a back-bridge relay, the operator on the line leading to telephone T^{10} will be selectively signalled so that she can intercept the call. But in the event that there is a local telephone in a Y connection the bell at telephone T^{10} will then be operated by 50-cycle current, due to relay Q^{16} being operated. Thus, this prevents a party in the main exchange from causing the bell at telephone T^{10} to be rung, calling in the operator instead, whereas a local party passing the call will cause the bell at telephone T^{10} to selectively ring the party thereat. That is to say, the arrangement provides for differentiating between the telephone T^{10} and the intercepting operator, depending upon whether the call is a direct one from the main exchange or it is one that has been passed, wherein the antecedent called local party remains in on the connection to, as it were, vouch that the main exchange party has the right to directly call the party at telephone T^{10} , who may be an executive who does not wish to respond to calls unless they have first been responded to by a subordinate, which may be his secretary-operator or an employee of his establishment who may be authorized to pass the call to his line.

Each telephone may have two differently selectively responsive bells

It will be noted in this connection that,

if desired, bells tuned for 33-cycles and 50-cycles may be installed contiguous to each telephone in the manner of connecting the relay A^{10} and the bell on the line leading to telephone T^{10} , and one or the other bell will be selectively rung to indicate the condition of the call; that it is a secret outside call, or is an outside call in which there is a local party in a Y branch to it. The use of the two differently tuned bells last referred to obviates attention to the speed of ringing the bell in the event that the single bell which may be used is not selectively responsive, with respect to the 33-cycle and 50-cycle signaling current.

It will be noted that the calling party at telephone A will hear the induction applied through the winding of the ring cut-off relay when a local telephone is being signaled so that the pitch of the tone will indicate if relay Q^{16} is actuated; that is, if the first called local party is holding his receiver off the switch-hook. Thus, the calling party at telephone A will know if there is a second party on the connection, with respect to the last called party.

Operator responds and extends connection

The actuation of the relay A^{10} causes relay B^{10} to be actuated and locked to the auxiliary spring on jack J^{10} , and this locking ground causes the lamp L^{10} to glow as a calling signal to the operator. The operator may then respond by inserting plug A^{11} , of the cord pair shown in Fig. 11, into jack J^{10} . The relay B^{10} will be unlocked and the lamp L^{10} will extinguish. The operator will manipulate listening key G^{11} , causing relays F^{10} and K^{16} in Fig. 16 to actuate, whereupon the operator will become in talking relation with the calling party at telephone A.

If the calling party at telephone A desires connection with the party at telephone T^{10} , the operator would withdraw plug A^{11} and insert the plug A^{11} into jack K^{10} and operate the ringing key E^{11} to apply 50-cycle signaling current to ring the bell. Noting that relay C^{10} is actuated, energized from the auxiliary spring of jack J^{10} , and that cord relay C^{11} is energized, the operator thus talks secretly with telephone T^{10} , the latter's transmitter being energized from the windings of the battery supply coil D^{11} .

At the time the operator answered the call with plug A^{11} in jack J^{10} , and perhaps also talked secretly with telephone T^{10} with plug A^{11} in jack K^{10} , she could withdraw the plug from jack K^{10} after the party at telephone T^{10} responded, whereupon relay C^{10} would deactivate, and relay D^{10} would actuate, energized in series with the telephone T^{10} . Lamp N^{10} will glow to indicate the busy condition, and will extinguish upon the party at telephone T^{10} hanging up.

Operator may pass call

It is noted that at the time the operator answered the call with plug A^{11} , she could have passed the call by manipulating key F^{11} , which would energize relay C^{10} , to cut off telephone T^{10} , and then operate the dial Z^{11} with correspondence to a desired local line, which would have set the wipers 701' to 704' of switch element Fig. 17 correspondingly. The operator, after passing the call, can remain in on the Y connection until a response has been obtained, or may withdraw the plug A^{11} and cause the switch element Fig. 16 to restore its wipers 610' to 613' over an obvious circuit path. That is, the operator may withdraw the plug before or after a response is received in a passing operation, but it is to be borne in mind that whether she disconnects before or after the response will determine the character of signaling current applied to the telephone to which the call has been passed, the signal bell operating and changing in accordance with what the operator did with respect to remaining in on the connection or disconnecting therefrom. 50-cycle signaling current will be applied until the plug A^{11} was removed, whereupon 33-cycle current will be applied to the telephone to which the call was passed.

Called local party may pass call to a holding circuit, then disconnect and call secretly and later come back and talk to the passed party on the holding circuit

If it is assumed that at the time the telephone Q^{10} was called, the party thereat desired to secretly confer with the party at some local or main exchange telephone while holding the connection made from telephone A to his telephone Q^{10} , he could do so in the following manner: He would pass the call to the holding circuit, shown in Fig. 9, by sending digits 4-1, corresponding to telephone number "41". This would cause the wipers 701' to 704' of switch element Fig. 17 to be set upon the bank terminals 720' to 723', and will then hang up, to cause the wipers 610' to 613' of switch element Fig. 16 to restore from his line.

At the time the wipers 701' to 704' were set upon bank terminals 720' to 723' ground is applied through wiper 702', conductor 723', to the winding of relay J^9 , the latter said relay and relay H^9 actuating.

It will be understood, in this connection, that the telephone Q^{10} has access to a line switch, not shown, and the latter has access to a connector-selector Q^9 , like shown in Fig. 8. That is, telephone Q^{10} and its line switch and connector-selector Q^9 corresponds to telephone T^8 in Fig. 8, as regards the line switch LS^8 and connector-selector Q^8 . The wipers and the first two sets of bank terminals of the 1 to 4 levels of a selector-connector Q^9 ,

like shown in Fig. 8 are indicated. So that the party at telephone Q^{10} , forthwith after hanging up, can remove his receiver and initiate an outgoing call through his line switch to the said connector-selector like shown in Fig. 8, and then operate this latter switch in the manner as has been described, with reference to Fig. 8, to call a local telephone, or a telephone in the main exchange over a 0 level trunk, and converse, and thereafter hang up and make a new call to the holding circuit. The holding circuit is shown connected to bank position "42" so that by reoperating the said connector-selector like Fig. 8 in accordance with telephone number "42", the wipers 901 to 904 will be set upon bank terminals 905 to 908. Ground applied from the private wiper 901 to conductor 909 will energize relay E^9 , which will close a circuit through the coil N^9 to pull up the ring cut-off relay (corresponding to F^8 in Fig. 8) in the connector-selector Q^9 , like Fig. 8, and also pull up the ring cut-off relay F^{17} in switch element Fig. 17, so that the party at Q^{10} is now again in talking relation with the calling party at telephone A. The first time the connection from the trunk line conductors 7-8 to the telephone Q^{10} was directly through the switch element Fig. 16, but now it is through the switch element Fig. 17 and the connector-selector Q^9 .

The release of the connection is as follows: If the party at telephone Q^{10} hangs up first and restores the connector-selector Q^9 , ground will be removed from conductor 909, causing relay E^9 to deactivate, opening the circuit energizing the back-bridge relay K^{17} , thereby causing the switch element Fig. 17 to restore its wipers 701' to 704'. And, if the party at telephone A should hang up while the party Q^{10} is off the connection, perhaps talking secretly with a party at another telephone, when the relay B^{18} deactuates, its upper spring will apply ground through off-normal spring of Fig. 17 to the release magnet to restore the wipers of the switch element Fig. 17.

Special toll trunk with duplex connector

With reference to diagram Fig. 26, which refers to a trunk line for long distance service between the main exchange toll switchboard to the private automatic exchange having the duplex connector Figs. 5-6, it will be pointed how a long-distance call is made to a local telephone line of the said private automatic exchange.

The long-distance trunk terminates in a duplex connector having interlinked elements 18 and 6. That is, element 18 is companioned with an element as Fig. 6 of the duplex connector Figs. 5-6 to make the new duplex connector Figs. 18-6. The toll switchboard end of the trunk is shown in Fig. 15.

It will be noted that the switch operating circuits disclosed in Fig. 5, excepting the circuits involved with the relays R^5 , S^5 , T^5 and P^5 correspond to the circuits disclosed in Fig. 18. So that in view of the descriptions relating to the operation of the duplex connector Figs. 5 and 6, the operation of the circuits in Figs. 18 and 6 combined into a duplex connector will be comprehended. The line relay A^5 in Fig. 5 corresponds to the line relay A^{18} in Fig. 18, only that the relay A^{18} has a single winding. The relay Q^{18} is added.

The toll operator in effecting connection to a local line accessible from the switch elements Figs. 18 and 6 (and also Figs. 5 and 6) will insert the plug P^{15} into the jack J^{15} . This will complete a circuit from the winding of line relay A^{15} , conductor 501', spring 502', ring of jack J^{15} , ring of plug P^{15} , make-before-break spring of key K^{15} , winding of relay A^{15} to ground, the relays A^{18} and A^{15} energizing in series. Lamp L^{15} will glow. The operator can now directly operate the switch element Fig. 18 by manipulating the dial key K^{15} to substitute the dial Z^{15} for the winding of the relay A^{15} , and then operating the dial in accordance with the telephone number of the desired local line. This will operate the line relay A^{18} in accordance with the dial and cause the vertical and rotary magnets of element Fig. 18 to correspondingly operate to set the wipers thereof upon the terminals of a desired local line, which may be assumed to be the line leading to telephone R^7 , the telephone number of which is "31".

The bell of the telephone R^7 will be operated from the ringing generator in Fig. 18, employing signaling circuits corresponding to the signaling circuits employed in the element Fig. 5. The party at telephone R^7 will cause the relays F^{18} , J^{18} and K^{18} to energize when he responds, in the manner as when relays F^5 , J^5 and K^5 were energized.

It is noted that when the relay K^{18} (or the relay K^6 in Fig. 6) energizes due to a responded condition, the relay Q^{18} will energize to remove the short-circuit from the resistor 503'. This will reduce the current strength energizing the winding of relay A^{15} below the sustaining value, so that the latter said relay will deactivate, and cause the lamp L^{15} to extinguish to indicate the response from the called local telephone.

The restoration of the wipers of the switch element Fig. 18 will be effected under the same conditions and employing corresponding circuits to those used in Figs. 5 and 6.

It will be noted that if no response is obtained from the telephone R^7 , or if the line had been encountered busy and relay E^{18} actuated in place of relay G^{18} , the impulse circuit will be closed to the winding of relay C^6 , and the toll operator may annex the digits of the telephone number of any other

accessible telephone and thereby operate the companion switch element Fig. 6 and set the wipers of the latter said switch element accordingly. And when the wipers of the latter said switch element are set upon the bank terminals of the desired line, off-normal ground in Fig. 6 is applied through either the upper spring on relay E⁶ or G⁶ to the upper off-normal spring in Fig. 18, and through the lower spring of relay K¹⁸ to the release magnet in Fig. 18, effective to restore the wipers of the switch element Fig. 18.

The toll operator may now await the response of the last called party, and when he responds the relay Q¹⁸ will be energized, responsive to the relays F⁶, J⁶ and K⁶ actuating, and this will cause the resistor 503' to be introduced into the path energizing the relay A¹⁵, causing it to retract its armature to glow the lamp L¹⁵.

In the event the last called party does not respond, or if the line were encountered busy and the relay E⁶ actuated, in place of relay G⁶, wherein the toll operator will then receive the busy-tone from source T¹⁸, the toll operator may thereupon annex the number of another local telephone line and set the wipers of the switch element Fig. 18 accordingly, the switch element Fig. 6 restoring its wipers responsive to either the relay E¹⁸ or G¹⁸ actuating, over a circuit path closed from the off-normal ground in Fig. 18, spring of either relay E¹⁸ or G¹⁸, spring on relay L¹⁸ and over an obvious path through upper off-normal spring in Fig. 6 to the release magnet, to restore the wipers of Fig. 6.

The toll operator may complete the connection from the jack J¹⁵ to any accessible line by means of the plug companion to the plug P¹⁵, not shown, of her cord-pair. The talking connection will be over the heavy conductors leading to the left from the tip and sleeve springs of the jack J¹⁵ to the duplex connector Figs. 18-6.

The switch-arms 505', 506' and 507' correspond in use to the switch-arms 540, 541 and 542, respectively, in Fig. 5.

Claims may be read on a plurality of the disclosed circuit organizations

While certain of the subjoined claims read upon a specific organization or part of the disclosed, comprehensive system, other claims will read upon a plurality of the organizations of the system. This is in view of the fact that certain operations and circuit organizations for carrying the operations into effect are present in more than one of the duplex switches.

The exemplary expression of the invention disclosed may be varied without departing from the scope of the claims.

I claim:

1. In a telephone system a first calling station, a line leading from said station to

an attendant's switchboard, means at said switchboard for extending said line to a duplex connector-switch, and means for successively actuating the elements comprising the control of said duplex connector-switch for the purpose of gaining access to second and third stations by applying successive series of impulses constituting telephone numbers.

2. In a telephone system a first calling station, a first line leading from said station to an attendant's switch-board, a means for extending said first line to a connector having access to a second line leading to a second station, means for placing said connector in connection with said second station whereby the privates of said trunk and said second station are made busy upon said second station becoming in a calling condition.

3. In a telephone system, a duplex connector, first and second lines leading from the connector bank, a trunk having its far end terminating at the incoming end of the connector, said connector being operable to transfer a call extending over the trunk to one line to the second line, and means for impressing one of two kinds of signalling current over a called line from the connector as the originating point of the signalling current in the connection depending upon whether the call is over the trunk or a transferred call.

4. A telephone system comprising a telephone line, a duplex connector, means for automatically operating the connector upon seizure thereof by said line as a calling line to select a predetermined set of bank contacts, and means for operating said connector over said contact to transfer the call to another line as a called line.

5. A telephone system comprising telephone lines, spring jacks for said lines, connector switches, said lines also terminating at the bank-contacts of the connectors, an operator's call-signal responsive to a connector operated by a call over a line, an operator's circuit, and means responsive to connection of the operator's circuit with the jack of the calling line to restore the connector for further use.

6. A telephone system comprising telephone lines, spring jacks and operator's individual call signals for the respective said lines, a connector common to the lines operated over a calling line to actuate the calling signal of the calling line, an operator's circuit, and means responsive to the connection of the operator's circuit with the calling line spring jack to restore the connector.

7. A telephone system comprising telephone lines, individual spring jacks and individual signals for said lines, a connector whereby a calling party may automatically connect with another one of said lines or may actuate his individual signal thru the con-

nect, and a plug ended cord circuit for thereupon connecting the spring jack of the calling line with a called line and release the connector for immediate further use.

8. A telephone system comprising an outside telephone line, inside or local telephone lines, a duplex connector, means whereby the outside line may operate said connector to connect with an inside line and whereby a called inside line may operate the connector to connect with another inside or local line while first said connection exists, and means at the substations on the inside lines to indicate whether the call is from an outside

15 or inside line.

9. In a telephone system a trunk line terminating in an automatic selector switch, other lines, means for operating said switch to select an idle one of said other lines including 20 automatic means for causing said switch to pass over busy lines, and additional means involving other bank terminals passed over by the switch for causing said switch to pass over all of said lines whether busy or not, 25 said last means comprising a circuit including a conductor of said trunk line.

10. In a telephone system, subscribers' lines of different character, trunk lines, and an automatic switch accessible to a calling 30 one of said subscribers' lines and controllable thereover to select an idle one of said trunk lines, including means for causing said switch to pass over the busy lines, and additional means involving other bank terminals passed 35 over by the switch for causing said switch to pass over either idle or busy lines, the operation of said last means depending on the character of the calling subscribers' lines.

11. In a telephone system, a calling line, 40 a called line, means for establishing a connection between said lines, a third line, an automatically operated hunting switch, means controlled by the called subscriber for initiating the hunting movement of said 45 hunting switch to extend the established connection in the direction of the third line, means controlled by the called subscriber for completing the extension of the established connection to said third line, and means 50 whereby the called line can be disconnected from the connection, leaving the calling line and the said third line connected.

12. In a telephone system, a calling line, 55 a called line, a selector switch and a connector switch for establishing a connection between said lines, a third line, an automatic step-by-step hunting switch individual to said selector, means controlled by the called subscriber for initiating the hunting movement of said hunting switch to extend the established connection in the direction of the third line, and means controlled by the called subscriber for further extending the established connection to said third line.

13. In a passing call system, main and

auxiliary rotary connectors permanently connected in pairs, means whereby a calling subscriber can directly operate one of said main connectors to select a group of lines, means for automatically operating said main connector to select an idle line of the selected group, means for controlling the associated auxiliary connector over the selected line to select another group of lines, and means for automatically operating the auxiliary connector to select an idle line in said other group, whereby the call is transferred from a line in one group to a line in another group.

14. In a passing call system, a main switch and means for operating it to extend a connection to a called line, an auxiliary switch associated with said main switch, groups of lines accessible to said auxiliary switch, means for operating said auxiliary switch over the connected called line to select one of said groups of lines, and means for then automatically operating said auxiliary switch to select and connect with an idle line in the selected group, whereby the call is transferred from the first called line to a line in one of said groups.

15. In a passing call system, main and auxiliary switches each having circuit arrangements providing for an automatic hunting movement, groups of lines accessible to said switches, means whereby a calling subscriber can operate said main switch to select one of said groups of lines, the main switch operating automatically thereafter to select and connect with an idle line in the selected group, and means for then controlling the auxiliary switch over the connected line to select another of said groups of lines, the auxiliary switch operating automatically thereafter to select and connect with an idle line in the second selected group, thus transferring the call from a line in one group to a line in another group.

16. In a passing call system, main and auxiliary switches, each having circuit arrangements providing for a subscriber controlled directive movement and an automatic hunting movement, groups of lines accessible to said switches, means whereby a calling subscriber can operate the main switch to select and connect with an idle line in a desired one of said groups, and means for thereafter operating said switches alternatively under called subscriber control to transfer and retransfer the call to idle lines in other of said groups.

17. In an automatic telephone system, a selective switch having primary and secondary wiper movements and a controlling line relay, means responsive to the energization of said relay for causing the wiper to operate from its restored position in a definite primary movement and thereupon automatically in its secondary movement, means

responsive to the momentary deenergizations of said relay for causing the wiper to operate from its restored position in its primary movement on correspondence with the number of said deenergizations, and means for thereupon causing the wiper to operate in its secondary movement.

18. In an automatic telephone system, a selective switch having primary and secondary wiper movements and a controlling line relay, a group of operator trunk lines and a group of other lines accessible from the wiper, means responsive to the energization of said relay for causing the wiper to operate from its restored position in a definite primary movement and thereupon automatically in its secondary movement to automatically selectively test for and seize an idle said operator trunk line, means responsive to the momentary deenergizations of said relay for causing the wiper to operate from its restored position in its primary movement in correspondence with the number of said deenergizations, and means for thereupon causing the wiper to operate in its secondary movement and to automatically selectively test for and seize an idle said other line.

19. In an automatic telephone system, a selective switch having primary and secondary wiper movements and a controlling line relay, a group of operator trunk lines and a group of other lines accessible from the wiper, means responsive to the energization of said relay for causing the wiper to operate from its restored position in a definite primary movement and thereupon automatically in its secondary movement to automatically selectively test for and seize an idle said operator trunk line, means responsive to one or more momentary deenergizations of said relay for causing the wiper to operate from its restored position in its primary movement in correspondence with the number of said deenergizations, and means for causing the wiper to operate in its secondary movement to automatically selectively test for and seize an idle line in the group of operator trunk lines or in the group of said other lines depending upon the extent of primary movement.

20. In a telephone system, a calling line terminating in a pair of switch elements, lines, a relay, means for operating a first one of said switch elements to effect connection with a first one of said lines, manually controlled means on the said first line to operate said relay, means for operating the second of said switch elements into connection with a second one of said lines forming a Y connection between the calling and the said first called and second called lines, means for thereafter disconnecting the said first called line without restoring the relay, means for then operating the said first element into

connection with the third said line forming a Y connection between the calling and the said second and third lines, means for thereafter disconnecting the said second line without restoring the relay, and means manually controlled from the said third line for restoring the relay.

21. In a telephone system, a trunk line, called lines, a pair of permanently companioned selective switches, other switches, means for selectively operating a first one of said pair of switches over the trunk to select one of said other switches, means for then operating said selected switch over the extended connection to select a first one of said called lines, means for then operating the other of said pair of selective switches and one of said other switches over said connection including said selected called line to select one of said called lines by last said switch to form a Y connection between the trunk line and said first and second said called lines, means for disconnecting said first called line connected while maintaining the connection to the second said called line, and means operated over said second connected called line for operating said first one of said pair of switches and one of said other switches to extend a connection to one of said called lines to form a Y connection between the latter said called line the second said called line and the trunk line.

22. In a telephone exchange system, a first exchange, subscribers' lines terminating therein, a second exchange, trunk lines extending between said exchanges, automatic switches at said first exchange, a line signal for each of said lines at said first exchange, and means under the control of a calling subscriber at said first exchange and operable over the two conductors of said line in series for selectively operating one of said automatic switches to extend said line to said second exchange or to operate the line signal of the calling line.

23. In a telephone system, calling lines, a signal device individual to each said line, an automatic connective switch common to said lines, a called line accessible from said switch, means for directively operating said switch over a random said calling line to connect the random calling line to the called line, and means for alternatively operating the switch responsive to a directive operation alike for all said calling lines applied over said random calling line for actuating the signal device individual to said random calling line.

24. In a telephone system, calling lines, a signal device individual to each said line, an automatic connective switch common to said lines, a called line accessible from said switch, means for directively operating said switch in common extent over a random said calling line to connect the random said call-

- ing line to the called line, and means for alternatively operating the switch in common extent but different from first said extent responsive to directive operation over said random calling line for actuating the signal device individual to said random calling line. 5 line, a signal device individual to said first local line, means for operating a first one of said switch elements to effect a connection from the leading-in line to the first local line, a second local line, means operable over the first local line by operator control to direct the operation of another of said switch elements to extend connection from the leading-in line to the second local line forming a Y connection between the leading-in line and the first and second lines, and means responsive to control from over the second local line and over the first local line to operate the signal device to indicate to the operator on the first local line that the said control over the second local line took place. 70
25. In a telephone system, a calling line, an automatic switch, two sets of wipers of the switch, a group of line terminals individual to each of the sets of wipers, means for directly operating the switch over the calling line to set one of the said wiper sets into hunting relation with the corresponding said terminals and for seizing one of said terminals to thereby connect the calling line with the seized terminals, means for then directly operating the switch over the calling line to set the other of said wiper sets into hunting relation with the corresponding said terminals and for seizing one of the latter said terminals to thereby connect the calling line with last said seized terminals, and means for preventing the calling line from being connected by more than one set of wipers at 15 a time to a said set of terminals. 75
26. In a telephone exchange system, a calling line, an impulse sender therefor, an attendant's position, a line signal thereat individual to said subscriber's line, a trunk circuit, and means responsive to one series of impulses from said impulse sender for actuating said line signal, and to another series of impulses to connect said line to said trunk circuit. 80
27. In a telephone exchange system, a calling line, an impulse sender therefor, an operator's position, a line signal thereat individual to said subscriber's line, a trunk circuit, and means individual to said line responsive to one series of impulses from said impulse sender for actuating said line signal and to another series of impulses from said impulse sender for connecting said line to 30 said trunk circuit. 85
28. In a telephone exchange system, a subscriber's line, an attendant's position, a line signal thereat individual to said line, a trunk circuit, means for sending impulses over the two sides of said line in series, and means responsive to one series of impulses over said line to actuate said signal and to another series of impulses to connect said line to said trunk circuit. 90
29. In a telephone exchange system, a calling subscriber's line, an attendant's position, a line signal individual to said line, a trunk circuit, an impulse sender for sending impulses over the two sides of said line in series, and relay means responsive to one series of impulses over said line to actuate said signal and to another series of impulses to connect said line to said trunk circuit. 95
30. In a telephone system, a leading-in line, automatic switch elements, a first local 100
- line, a signal device individual to said first local line, means for operating a first one of said switch elements to effect a connection from the leading-in line to the first local line, a second local line, means operable over the first local line by operator control to direct the operation of another of said switch elements to extend connection from the leading-in line to the second local line forming a Y connection between the leading-in line and the first and second lines, and means responsive to control from over the second local line and over the first local line to operate the signal device to indicate to the operator on the first local line that the said control over the second local line took place. 105
31. In a telephone system, a plurality of leading-in lines and terminating individual line switches therefor, a signal device individual to each said line, a connective switch common to said leading-in lines, a jack for each of said leading-in lines, means responsive to initiating a call on a random one of said leading-in lines for thereby causing connection to be effected from said random line to said common connective switch, means thereupon operated over said random line to directly operate the connective switch, means depending upon the particular operation of the connective switch for causing the signal device of the said random line to operate to indicate which particular line is the random line, and means for manually connecting to the jack to thereby connect to the random line and disconnect the connective switch from the connection, subject to new use. 110
32. In a telephone system, a leading-in line, an automatic connective switch terminating said leading-in line, a local line, means for operating said switch to effect connection from the leading-in line to the local line, a holding circuit, means operated over the local line for changing the connection from the leading-in line to the holding circuit in lieu of the local line in freeing the local line, and means whereby the local line can by directive operation over the local line regain connection with the leading-in line via the holding circuit. 115
33. In a telephone system, a calling line terminating in a pair of switch elements, the said calling line having a total of exactly two combined talking and operating conductors at a point intermediate of its ends, lines, means for operating a first one of said switch elements over said two conductors of the calling line to effect connection with a first one of said lines, means for operating the second of said switch elements into connection with a second one of said lines forming a Y connection between the calling and the said first called and second called lines, means for thereafter disconnecting the said first called line, means for then operating the said 120
- 125
- 130

first element into connection with a third said line forming a Y connection between the calling and the said second and third line, means for impressing one of two kinds of signalling current to the line called depending upon whether it is the first said line called or is the second or third said line called, and means whereby said signalling current is impressed from a point intermediate of the calling line and the line called.

34. In an automatic telephone system, an automatic switch, a leading-in line for the switch, a line-connecting wiper of the switch, levels of groups of lines accessible from the wiper, sub-groups of said level groups, means operated responsive to effecting a closed circuit of the leading-in line for causing the wiper to operate from normal to select a predetermined one of said levels and a sub-group thereof, means for restoring the wiper to normal, and means then operative responsive to directly effecting open impulses of said circuit of the leading-in line for correspondingly operating the wiper from normal to select a desired random one of said levels and a desired random sub-group thereof.

35. In an automatic telephone system, an automatic switch, a leading-in line for the switch, a line-connecting wiper of the switch, levels of groups of lines accessible from the wiper, means operated responsive to effecting a closed circuit of the leading-in line for causing the wiper to operate from normal to select a predetermined one of said levels, means for restoring the wiper to normal, and means then operative responsive to directly effecting open impulses of said circuit of the leading-in line for correspondingly operating the wiper from normal to select a desired one of said levels.

36. In an automatic telephone system, an automatic switch, a leading-in line for the switch, a line-connecting wiper of the switch, levels of groups of lines accessible from the wiper, means operated responsive to effecting a closed circuit of the leading-in line for causing the wiper to operate from normal to select a predetermined one of said levels and a line of the level, means controlled over last said line for restoring the wiper to normal, and means operated by effecting open impulses of said closed circuit for again causing the wiper to select said line of the level.

37. In an automatic telephone system, an automatic switch, a leading-in line for the switch, a line-connecting wiper of the switch, levels of groups of lines accessible from the wiper, means operated responsive to effecting a closed circuit of the leading-in line for causing the wiper to operate from normal to select a predetermined one of said levels and a line of the level, means controlled over the leading-in line for restoring the wiper to normal, and means operated by effecting open

impulses of said closed circuit for again causing the wiper to select said line of the level.

38. In a telephone system, an automatic switch, a connecting wiper of the switch, levels of lines accessible from the switch, a leading-in line of the switch, means for operating the wiper from normal position to select a level and to hunt along the level to connect with an idle line thereof responsive to initiating a call on the leading-in line by closing a circuit thereof, means for restoring the wiper to normal position and maintaining it so while maintaining the call initiated, and means operated responsive to directive step-by-step automatic control of the switch for operating the switch to select said level and to hunt along said level to connect with an idle line thereof, while maintaining said call initiated.

39. In a telephone system, an automatic switch mechanism, a circuit of said switch mechanism, means for causing said switch mechanism to operate in predetermined extent responsive to sustainingly energizing said circuit, and means for again causing said switch mechanism to operate in said predetermined extent responsive to momentarily deenergizing said circuit.

40. In a telephone system, a calling line, automatic switch mechanism accessible from the calling line, an operator's answering line having not to exceed two conductors, automatic means operated responsive to manual operation on the calling line for causing the calling line to become connected with the answering line, called lines, means under control of the operator over the operator's answering line for directly operating the switch mechanism for extending a connection from the calling line to a desired random one of said called lines from a point intermediate of the calling line and the operator's answering line, and means for freeing the operator's answering line from the connection while thereafter maintaining the connection from the calling line to the called line.

41. In a telephone system, automatic switch mechanism, a leading-in line for the switch mechanism, an answering line having not to exceed two conductors, means for causing the leading-in line to be connected with the answering line responsive to a maintained circuit closure occurring on the leading-in line, a called line, means controlled over the answering line for directly operating the switch mechanism to extend the connection to the called line, and means operable for freeing the answering line from the connection, leaving the leading-in line and the called line connected.

42. In a telephone system, automatic switch mechanism, a leading-in line for the switch mechanism, an answering line having not to exceed two talking conductors, means respon-

sive to initiating a call on the leading-in line resultant from a manual operation therefor for causing the leading-in line to be connected with the answering line, a called line, means controlled over the answering line for directively operating the switch mechanism to extend the connection to the called line, and means then operable for freeing the answering line from the connection, leaving the leading-in line and the said called line connected.

43. In a telephone system, automatic switch mechanism, a leading-in line for the switch mechanism, an answering line having not to exceed two conductors, means responsive to control over the leading-in line for causing the leading-in line to be connected to the answering line, a called line, means controlled over the answering line for directively operating the switch mechanism to extend the connection to the called line, and means operable over the called line for freeing the answering line from the connection, leaving the leading-in line and the called line connected.

44. In a telephone system, automatic switch mechanism, a leading-in line for the switch mechanism, an answering line having not to exceed two conductors, means responsive to control over the leading-in line for causing the leading-in line to be connected to the answering line, a called line, means controlled over the answering line for directively operating the switch mechanism to extend the leading-in line to the called line, a signal device for the answering line, means operable over the called line for freeing the answering line from the connection, leaving the leading-in line and the called line connected, and means operated over the answering line for causing the signal device to operate whereby the party on the answering line will know thereby when the answering line becomes free from the connection.

45. In a telephone system, automatic switch mechanism, a leading-in line for the switch mechanism, an answering line having not to exceed two conductors, means responsive to control over the leading-in line for causing the leading-in line to be connected to the answering line, a called line, means controlled over the answering line for directively operating the switch mechanism to extend the leading-in line to the called line, a signal device for the answering line, means operated over the answering line for causing the signal device to operate whereby the party on the answering line will know thereby when the response is made on the called line, and means whereby the answering line may be employed in a new connection while the said extension from the calling line to the called line is sustained.

46. In a telephone system, automatic switch mechanism, a calling line, an answering line having not to exceed two conductors, a selective switch, means operated responsive to con-

trol from the calling line for operating the selective switch to connect the answering line and calling line together, a called line, means controlled over the answering line for operating the automatic switch mechanism to extend connection from the calling line to the called line, and automatic means for freeing the answering line from the connection, leaving the calling line and the called line connected.

47. In a telephone system, automatic switch mechanism, a calling line, a telephone, means for connecting the telephone in talking relation to the calling line, an answering line having not to exceed two conductors, a selective switch, means independent of first said means operated responsive to control from the calling line for operating the selective switch to connect the answering line and calling line, a called line, means controlled over the answering line for operating the automatic switch mechanism to extend connection from the calling line to the called line, and automatic means for freeing the answering line from the connection, leaving the calling line and the called line connected.

48. In a telephone system, automatic switch mechanism, a calling line, a telephone, means for connecting the telephone in talking relation to the calling line, an answering line having not to exceed two conductors, a selective switch, means independent of first said means operated responsive to control from the calling line for operating the selective switch to connect the answering line and calling line, a called line, means controlled over the answering line for operating the automatic switch mechanism to extend connection from the calling line to the called line, automatic means for freeing the answering line from the connection, leaving the calling line and the called line connected, a second answering line, and means operated over the called line for operating said selective switch to extend a Y connection from a point intermediate of the calling line and the called line to said second answering line.

49. In a telephone system, automatic switch mechanism, a calling line, an answering line having not to exceed two conductors, a selective switch, means operated responsive to control from the calling line for operating the selective switch to connect the answering line and calling line together, a called line, means controlled over the answering line for operating the automatic switch mechanism to extend connection from the calling line to the called line, automatic means for freeing the answering line from the connection, leaving the calling line and the called line connected, a second answering line, and means operated over the called line for operating said selective switch to extend a Y connection from a point intermediate of

the calling line and the called line to said second answering line.

50. In a telephone system, a calling line, an answering line having not to exceed two conductors, first automatic switch mechanism under control of the calling line for connecting the answering line with the calling line, second automatic switch mechanism, called lines, means for directly operating said second automatic switch mechanism from the answering line to extend connection from the calling line to a desired one of said called lines, forming a Y connection between the calling line, the answering line and the called line, and means thereafter at will controlled over the answering line for disconnecting the answering line from the connection subject to new use, while leaving the calling line and the line called in connection.

51. In an automatic telephone system, an automatic switch, a called line, a calling line for connection to said switch, means controlled over the calling line for extending connection by the switch from the calling line to the called line, automatic means for disconnecting said connection from the called line while maintaining connection from the calling line to the switch, automatic means for then operating the switch into connection with the called line while said connection from the calling line to the switch is maintained, two signal devices on the called line operated from the switch, and means whereby depending upon whether the connection to the called line is the first connection thereto or a subsequent connection thereto of a single initiated call, for determining which said signal will be operated from the automatic switch.

52. In an automatic telephone system, a switch, a pair of talking conductors leading-in to the switch, a reversing relay for the switch operated for reciprocating the relation of said conductors with respect to the switch, a called line, means for operating the switch from normal to extend connection from the leading-in line to the called line, means controlled over the called line from a response thereon for effectively operating the reversing relay, means for restoring the switch from its connection with the called line to normal while maintaining the relay operated thereafter, and means controlled at will over said pair of conductors for restoring the relay to its unoperated state.

53. In an automatic telephone system, an automatic switch, leading-in conductors for said switch, calling lines of two classes, a switch individual to each said calling line, means for connecting the various calling lines via their respective individual switches to the automatic switch one at a time over all said leading-in conductors for all connections to the automatic switch, a called line accessible from said switch, and means

operated over one of said leading-in conductors for barring calling lines of only one class from connecting with said called line.

54. In an automatic telephone system, an automatic switch, leading-in conductors for said switch, a marginal relay individual to said switch, a called line, calling lines of two classes, a relay for each calling line, the windings of said relays having high or low resistance depending on the class of its line and adapted to be placed in series with a conductor of the leading-in line and the relay individual to the switch when said line is called, means for extending connection from a random one of said calling lines to the switch via the leading-in conductors, and means including said marginal relay and the said relay of the line calling in a series path of a conductor of the leading-in line depending upon to which class the calling line belongs for barring the called line from being connected to by the switch.

55. In a telephone system, a line, an operator's switchboard at one end of said line, branches of said line at the other end of said line from the operator's switchboard end, automatic switches for extending said branches, respectively, other lines, and means whereby the operator can directly control said switches one at a time to establish a three-way talking circuit including the operator's switchboard and two of said other lines.

56. In a telephone system, a trunk line having not to exceed two conductors, a pair of automatic switches, groups of line terminals accessible from each said switch, means for directly operating a first one of said switches over the trunk line to select a group of lines, automatic means for thereupon hunting over the group to connect the trunk line with the first idle line of the group encountered, means for then directly operating the other one of said switches over the trunk line to select a group of lines, automatic means for thereupon hunting over the group to connect the trunk line with the first idle line of the group encountered to form a three-party Y connection of the trunk line and the two lines connected to by the switches, and automatic means for disconnecting one or the other of said switches from the line connected to in readiness for reoperating it to connect with a line same as before.

57. In a telephone system, a selector and a connector switch, means for operating said switches in succession to connect with a called subscriber's line, and means under the control of the said called subscriber to reoperate said selector switch before the calling subscriber hangs up.

58. In a telephone system, a selector switch, connector switches accessible thereto, means for operating said selector and one of said connectors to connect with a called line, means under the control of the subscriber on

said line to reoperate said selector switch and another connector switch to pass the call to a second called subscriber.

59. In a telephone system, automatic selector switches, connector switches accessible thereto, means controlled by a calling subscriber for seizing a selector switch and for then operating it to select one of said connector switches, and for operating said connector switch to find a called line, together with means controlled from the called line over a part of said extended connection for operating said first seized selector and another connector to extend a connection to a second called subscriber.

15 60. In a telephone system, a trunk line, means for extending a connection from said trunk line to a called subscriber's line through a plurality of successively operated switches, 20 and means controlled from the called line for extending the connection to a second called party by reoperating one of said switches used in said first established connection.

25 61. In a telephone system, a selector having
two sets of connecting wipers, a leading-in
line for the selector, means controlled over
the leading-in line for causing one of said
sets of wipers to hunt over a line group and
seize the first idle line encountered, and
means controlled over the line seized for caus-
ing the other set of wipers to hunt over an-
other line group and seize the first idle line
encountered and for freeing the first said
line seized.

35 62. In a telephone system, a selector having two sets of connecting wipers, a leading-in line for the selector, means controlled over the leading-in line for causing one of said sets of wipers to hunt over a line group
40 and seize the first idle line encountered, and means controlled over the line seized for causing the other set of wipers to hunt over another line group and seize the first idle line encountered.

45. 63. In a telephone system, a line, means for seizing said line, means on said line responsive to said seizure for applying signalling current ahead on said line from a point on said line, and means controlled over the 50 part of said line traversed by said signalling current for stopping the application of the signalling current.

64. In a telephone system, a line, means for seizing said line, a source of current to which a condenser is transparent, and means on said line responsive to said seizure for applying said source of current ahead on said line.

65. In a telephone system, a subscriber's line, a link circuit common to other lines for temporary connection to said subscriber's line, a source of signalling current in said link, means for connectively seizing to said link circuit to effect connection with said 65 connected subscriber's line, means respon-

sive to said seizure for causing said signalling current to be applied to the subscriber's line, and means controlled over the subscriber's line for stopping the application of the signalling current.

66. In an automatic telephone system, a connective switch, lines accessible from said switch, a trunk line leading in to said switch, automatic switch means for seizing said trunk line, means operated responsive to seizing said trunk for placing a bar on said trunk to prevent more than one said seizure thereof existing at one time, means operated over said connection to direct the operation of said switch from normal to extend connec- 75 30

tion to a desired one of said accessible lines, means for causing signaling current to be applied to the connected-to line, means controlled over the last said line for stopping the application of signaling current, means controlled over said trunk from a point of the connection antecedent to the trunk for restoring the connective switch to normal, means for disabling last said means for restoring the switch from the connected-to line, while at the same time enabling the connection to the trunk to be thereby broken down, means whereby under the said disabled condition the bar for the trunk will be removed at the time the connection is broken down, means for again seizing the trunk and for thereupon placing a bar thereon and for also causing the said signaling current to be again applied to the connected-to line, and means controlled over the latter said line for stopping the application of signaling current.

67. In a telephone system, an automatic switch, a leading-in line for the switch, lines accessible from said switch, means operated over the leading-in line for directively setting the switch into connective relation with a desired one of said lines, means controlled over the leading-in line for restoring the switch from the line connected with the set switch, means for rendering the set switch disabled from restoring, and switch means for connecting and disconnecting from the connected one of said lines via the leading-in line and the set switch a plurality of times while the switch remains in its set position. 115

68. In a telephone system, an automatic switch, a leading-in line for the switch, lines accessible from said switch, means operated over the leading-in line for directively setting the switch into connective relation with a desired one of said lines, means controlled over the leading-in line for restoring the switch from the line connected with the set switch, means for rendering the set switch disabled from restoring, switch means for connecting and disconnecting from the connected one of said lines via the leading-in line and the set switch a plurality of times while the switch remains in its set position, 120
125
130

5 a busy bar terminal for each of said lines to prevent more than one connection thereto at one time, and means for placing the bar on the line upon which the switch is set responsive to said switch means connecting to the leading-in line and for removing the bar responsive to the said switch means being disconnected from the leading-in line.

10 69. In a telephone system, an automatic switch, a leading-in line for the switch, subscribers' lines accessible from said switch, means operated over the leading-in line for directly setting the switch into connective relation with a desired one of said lines, 15 means controlled over the leading-in line for restoring the switch from the line connected with the set switch, manual switch means for rendering the set switch disabled from restoring, and switch means for connecting and 20 disconnecting from the connected one of said lines via the leading-in line and the set switch a plurality of times while the set switch remains in its set position.

25 70. In a telephone system, called lines, a leading-in line, an automatic switch for extending connection away from the leading-in line to a desired one of said called lines, another automatic switch having access to said called lines in common with first said switch, 30 means for automatically directly operating first said switch to set it upon the terminals of a desired one of said called lines, means whereby first said switch can be maintained set upon the terminals of said desired 35 called line without being in seizure of last said line, and means in the set first said switch thereafter at will operated over the leading-in line for causing first said switch to seize last said line by applying a busy bar to it to thereby prevent said another switch from being able to seize last said line.

40 71. In a telephone system, called lines, a leading-in line, an automatic switch for extending connection away from the leading-in line to a desired one of said called lines, another automatic switch having access to said called lines in common with first said switch, a busy bar conductor of the respective said called lines for guarding the corresponding line against seizure by said switches, means 45 for automatically directly operating first said switch to set it upon the terminals of a desired one of said called lines, means whereby first said switch can be maintained set upon the terminals of said desired called line without changing the potential of the bar conductor of the corresponding line from that existing when its line is in its idle unbarred state, and means in the set first said switch 50 thereafter at will operated over the leading-in line for causing first said switch to place a predetermined guarding potential on the bar conductor of the called line the first said 55 switch is set upon to thereby prevent said

another switch from being able to seize last said line.

72. In a telephone system, a trunk line, called lines, an automatic switch for extending connection from the trunk line to a desired one of said called lines, an impulse circuit involving at least one of the conductors of the trunk line, current for energizing said impulse circuit in a predetermined polarity direction, means for effecting impulses of 75 said energized circuit to thereby directly operate the switch to link the extension from the trunk to a desired one of said called lines, and means operated responsive to the switch completing the connection to the terminals of 80 the desired called line when idle for causing the direction of current energizing the impulse circuit to be reversed in direction.

73. In a telephone system, a trunk line, called lines, an automatic switch for extending connection from the trunk line to a desired one of said called lines, an impulse circuit involving at least one of the conductors of the trunk line, current for energizing said impulse circuit in a predetermined polarity 85 direction, means for effecting impulses of said energized circuit to thereby directly operate the switch to link the extension from the trunk to a desired one of said called lines, and means operated responsive to the switch 90 completing the connection to the terminals of the desired called line when busy for causing the direction of current energizing the impulse circuit to be reversed in direction.

74. In a telephone system, a trunk line, 100 called lines, a common automatic switch with relation to said trunk line and also said called lines for extending connection from the trunk line to a desired one of said called lines, an impulse circuit involving at least one of the 105 conductors of the trunk line, current for energizing said impulse circuit in a predetermined potential, means for effecting impulses of said energized circuit to thereby directly step-by-step operate the switch to link the extension from the trunk to a desired one of said called lines, means operated responsive to the switch 110 completing the connection to the terminals of the desired called line when idle for causing the said potential of current energizing the impulse circuit to be changed, and a relay of the connection located antecedent to the said automatic switch and operated over said impulse circuit responsive to said change in potential of said impulse circuit.

75. In a telephone system, a trunk line, called lines, a common automatic switch with relation to said trunk line and also said called lines for extending connection from the trunk line to a desired one of said called lines, an 115 impulse circuit involving at least one of the conductors of the trunk line, current for energizing said impulse circuit in a predetermined potential, means for effecting impulses of said energized circuit to thereby directly 120

step-by-step operate the switch to link the extension from the trunk to a desired one of said called lines, means operated responsive to the switch completing the connection to the terminals of the desired called line when busy for causing the said potential of current energizing the impulse circuit to be changed, and a relay of the connection located antecedent to the said automatic switch and operated over said impulse circuit responsive to said change in potential of said impulse circuit.

76. In a telephone system, a trunk, an automatic switch terminating the trunk, a line accessible from said switch, other switches having access to said line in common with first said switch, means for setting said switch into selective relation with said line, without making said line busy to thereby bar it against seizure by one of said other switches, and means operated over the trunk for causing the set switch to make said line busy.

77. In a telephone system, a trunk, an automatic switch terminating the trunk, a line accessible from said switch, other switches having access to said line in common with first said switch, means for setting said switch into selective relation with said line, without making said line busy to thereby bar it against seizure by one of said other switches, means operated over the trunk for causing the set switch to make said line busy and to at the same time continuously apply signaling current to said line, and means operated over said line for stopping the application of the signaling current.

78. In a telephone system, a trunk, an automatic switch terminating the trunk, a line accessible from said switch, other switches having access to said line in common with first said switch, means for setting said switch into selective relation with said line, without making said line busy to thereby bar it against seizure by one of said other switches, means operated over the trunk for causing the set switch to make said line busy and to at the same time continuously apply signaling current to said line, means operated over said line for stopping the application of the signaling current, and means operated over the trunk for again causing the switch to apply signaling current to said line while the switch is maintained in selective relation with said line.

79. In a telephone system, a trunk, an automatic switch terminating the trunk, a line accessible from said switch, other switches having access to said line in common with first said switch, means for setting said switch into selective relation with said line, without making said line busy to thereby bar it against seizure by one of said other switches, means operated over the trunk for causing the set switch to make said line busy, and

means operated over said line for disabling last said means from becoming effective.

80. In a telephone system, a trunk, an automatic switch terminating the trunk, a line accessible from said switch, other switches having access to said line in common with first said switch, means for setting said switch into selective relation with said line, without making said line busy to thereby bar it against seizure by one of said other switches, means operated over the trunk for causing the set switch to seize the trunk, and means operated over said line after the switch has been set to disable last said means from becoming effective.

81. In a telephone system, a trunk, an automatic switch terminating the trunk, a line accessible from said switch, other switches having access to said line in common with first said switch, means for setting said switch into selective relation with said line, without making said line busy to thereby bar it against seizure by one of said other switches, means operated over the trunk for causing the set switch to seize the trunk, and means operated over said line after the switch has been set to disable last said means from becoming effective and for applying a tone to a talking conductor of the trunk.

82. In a telephone system, a trunk, an automatic switch terminating the trunk, a line accessible from said switch, other switches having access to said line in common with first said switch, means for setting said switch into selective relation with said line, without making said line busy to thereby bar it against seizure by one of said other switches, means for seizing the trunk, means operated responsive to said seizure for causing the set switch to seize said line, and means operated over said line for disabling last said means from becoming effective and for applying a tone to a talking conductor of the trunk to indicate that a seizure of said line by the switch is barred.

83. In a telephone system, a trunk, a plurality of switch elements terminating said trunk, lines accessible from said elements, means for successively operating said elements one at a time to connect the trunk to respective ones of said lines, a relay energized for reciprocating the relationship of the talking conductors of the trunk, means for energizing said relay upon the first response from a connected said line, and means for maintaining the relay energized only so long as a random one of said lines connected to is in a responded state.

84. In a telephone system, a trunk, the winding of a first relay connected in a bridge of the trunk, the winding of a second relay, and means rendered effective responsive to energizing the winding of said first relay for substituting therefor the winding of said second relay in bridge of the trunk.

85. In a telephone system, a trunk, the winding of a first relay and source of energizing current connected in a bridge of the trunk, the winding of a second relay and source of current, and means rendered effective responsive to energizing the winding of said first relay for substituting therefore the winding and its source of energizing current of said second relay in bridge of the trunk.
- 10 86. In a telephone system, a trunk having two sections, a relay having its winding in a bridge of the respective sections, means for energizing a first one of said relays over its corresponding section, and means responsive to the energization of said first one of the relays for joining the sections to thereby energize the relay of the other section of said sections and for disconnecting the winding of first said relay from its section.
- 20 87. In a telephone system, a trunk, an automatic switch terminating the trunk, a relay individual to the trunk having its winding connected in bridge of the trunk operated over the trunk to in turn operate the switch, and a second relay individual to the trunk for controlling the switch which has its winding substituted for that of the first mentioned relay consequent to the operation of the first mentioned relay.
- 30 88. In a telephone system, an automatic switch, a leading-in line for the switch, a called line reached via the switch, a bridge path closed across the trunk for sustaining the switch in connection with the called line, and means controlled over the called line for opening the bridge path to thereby cause the switch to disconnect from the called line.
- 40 89. In a telephone system, an automatic switch, a leading-in line for the switch, a called line reached via the switch, a bridge path closed across the trunk for sustaining the switch in connection with the called line, although there is no circuit path of the switch closed over the called line, means for then closing a circuit path of the switch over the called line while maintaining said bridge path closed, and means for opening said bridge path to cause the switch to disconnect from the called line responsive to opening said circuit closed over the called line.
- 50

In witness whereof, I have hereunto subscribed my name this third day of December, 1930.

HERBERT M. FRIENDLY.
